PHONOGRAPH

Clemma R. Raney, Riverside, Ill.

Application June 17, 1927, Serial No. 199,605

198 Claims. (Cl. 274—10)

My invention relates to phonographs.

It has been among its objects to provide an improved phonograph of the automatic type. A further object is to provide an improved machine capable of automatically playing, or reproducing and discharging one, or a series of selected records. Additional objects of my invention are to produce an improved automatic machine which can be started automatically by the mere insertion of the record or records in the machine, and one which permits new records to be supplied to it, or certain of the records previously selected to be removed from it, or to be replaced, all while the machine is in operation. Still further objects are to provide an improved automatic machine adapted to be automatically set as records are inserted therein, to reproduce automatically all records therein, and one which is also adjustable at the will of the operator to change the setting at any time during the operation of the machine, to start or stop the machine, or to reject records, as well as an improved machine wherein the condition of the machine is indicated clearly at all times in a new and improved manner. Other objects of my invention include the provision of improved mechanisms functioning to bring about the playing or reproduction of a record or a series of records including improved means for adjusting the machine for records of different sizes, an improved record magazine, improved record releasing and feeding mechanisms, improved reproducer adjusting mechanism, improved record discharging means, improved setting and indicating mechanisms, and various improved controlling means associated with the several mechanisms. Still other objects include the provision of a simple construction embodying the combined mechanisms so compactly disposed and ruggedly constructed that it may be manufactured cheaply, installed in a convenient form in a cabinet of relatively small size, and operated over a long period without danger to derangement of its mechanism. These and other objects and advantages of my improved construction will, however, hereinafter more fully appear.

In the accompanying drawings I have shown for purposes of illustration one embodiment which my invention may assume in practice.

In these drawings,—

Figure 1 is a plan view of a phonograph cabinet equipped with my improvement, the table being removed and certain parts being indicated in dotted lines or broken away to facilitate illustration;

Fig. 2 is a side elevation, partially in section, of the mechanism shown in Fig. 1, the table being

shown in full lines therein and the magazine mechanism being shown in different positions of adjustment;

Fig. 3 is an end view showing a portion of the controlling mechanism;

Fig. 4 is an end elevation of a portion of the magazine mechanism shown in Fig. 2;

Fig. 5 is a detail side elevation of the record latch mechanism showing the same in a different angular position from that shown in Fig. 2;

Fig. 6 is a detail sectional view on line 6—6 of Fig. 3;

Fig. 7 is a detail sectional view on line 7—7 of Fig. 1;

Fig. 8 is a sectional view on line 8—8 of Fig. 1;

Fig. 9 is an enlarged plan view of the starting and stopping mechanism;

Fig. 10 is a side elevation of the mechanism shown in Fig. 9;

Fig. 11 is an enlarged plan view of the reproducer controlling mechanism shown in Fig. 1;

Fig. 12 is a side elevation, partially in section, of the latter mechanism, and

Fig. 13 is a combined view showing the several cams in side elevation when straightened for facility of illustration.

In this illustrative construction I have shown a mechanism of vertically compact form located above a suitable machine motor 1 and disposed in planes above and below a rotating table 2 rotatable by that motor on an upright axis; a sound box 3 being adapted to move across a record on the table 2 and improved means hereinafter described being provided whereby a record or a series of records dropped from a magazine at the left of the table (Fig. 2) may be supplied laterally to the right to the table 2, reproduced, and discharged therefrom to the right as indicated in dotted lines in Fig. 2, and whereby the machine and the several mechanisms thereof may be controlled, all in an improved manner.

Referring to the general structure more specifically, it will be noted that the mechanism is, generally speaking, disposed very compactly vertically. Herein, the table 2 rotates with a shaft 4 extending upward from the motor, being disposed on the upper end of this shaft and above a main casting 5 supported on the motor casing and also above a flat main plate or base 6 supported on the main casting 5. It will also be noted that the major portion of the operating mechanism is so disposed beneath the base 6 as to be covered thereby, and that the small amount of mechanism disposed above the base is, furthermore, disposed in substantially the planes of movement 55

of the reproducer sound box 3 in such manner as to produce the vertically compact machine mentioned. Attention is also directed to the fact that the mechanism below the base 6 is compactly disposed vertically, being disposed substantially between the base 6 and the plane of the top of the motor 1, while the latter is also of vertically compact type, these features further acting to increase the vertically compact character of the mechanism.

In this construction, improved mechanism is provided for enabling the machine to operate upon records of different size, as, for example, ten or twelve-inch records, at the option of the operator, and as the preparation of the machine to operate on records of a given size may be a preliminary to the use of the machine, this mechanism will be first described.

Herein it will be noted that improved record guiding means are provided above the base 6 and at each side of the table 2. This means includes a pair of record guiding members 7 which extend longitudinally in parallel relation. Each of these members 7 has a horizontal base portion or flange resting on the base 6 and an outer vertical upstanding flange adapted to engage the records and extending up above the top of the table 2. As shown, the horizontal flange of each of these members 7 is also provided with a plurality of depending pins 8 disposed at opposite ends thereof and movable therewith, and each having a suitable projecting washer adapted to move in a diagonal slot 9 formed in the base 6, these slots 9 herein extending outwardly and toward the left from the member 7, with the slots on each side of the table 2 in parallelism. Herein, one of the pins 8 is connected to the extreme left-hand end of each member 7, as shown in Fig. 1, while the other pin is connected to its member 7 slightly farther from its opposite end. Thus it will be noted that means are provided whereby the member 7 may be moved from the full-line to the dotted-line position shown in Fig. 1 in such manner as to adapt them to guide records of different diameter to the table 2.

Cooperating with these adjustable guides 7 is an improved adjustable magazine, likewise adapted to accommodate records of different size. Herein, one element of this magazine requires no adjustment and comprises an upright rotating chain 10 forming a record support and movable about a lower sprocket 11 and an upper guide roll 12, both carried on a suitable support, hereinafter described, and also operatively connected to record releasing mechanism, likewise hereinafter described. Here it will be sufficient to say that this chain mechanism 10 is disposed slightly to the left of and adjacent the axis of the table 2, as shown in Fig. 2, so that it presents a series of record supporting means adapted to support a series of records, as shown in Fig. 2. As shown in Figs. 1 and 2, the magazine mechanism also includes a cooperating record support 13 carried on an upstanding member 14 suitably spaced to the left from the chain 10. Herein the member 13 is round (Fig. 2) with a reversely tapering portion of reduced diameter between its ends (Fig. 1), and thus forms a support for the opposite edge of a record supported on the bottom link 70 of the chain 10, as shown in Fig. 2, especially adapted to permit the release of the bottommost record when the chain 10 is actuated as hereinbefore described, and also to direct the record laterally toward the table. This member 13 is hereinafter described, and also to direct the record laterally toward the table. This member 13 is here- 75 in also laterally movable to adapt it to cooperate

with records of different size, the same moving with the member 14 when the latter is adjusted to the right or left in a suitable longitudinal slot 14^a in the base 6, as indicated by full and dotted lines in Fig. 2.

It will also be noted that improved means are provided whereby an adjustment of the member 14 to accommodate records of different size is caused to be transmitted to the guides 7 heretofore described, to cause a corresponding adjustment of the latter. Herein when the upstanding member 14 is moved from the full-line to the dotted-line position shown in Fig. 2, or vice versa, a longitudinally extending member 15, disposed beneath the base 6, is moved longitudinally therewith and carries with it a crossbar 16 having transverse slots 17 in its outer ends, likewise adapted to receive the pins 8. Thus, for example, when the member 14 is moved two inches outward in the slot 14^a, i. e. to the dotted-line position shown in Fig. 2, to accommodate a twelve-inch or other than a ten-inch record, the crossbar 16 is caused to move from the right-hand dotted-line position shown in Fig. 1 to the left-hand dotted-line position shown therein, and consequently causes the members 7 to move from the full-line positions illustrated in Fig. 1 to the dotted-line positions shown therein. It will also be noted that a spring pressed ball 15^a carried by the base 6 and adapted to seat in holes 15^b longitudinally spaced in the bottom of the member 15, serves to hold that member definitely in either position. Attention is also directed to the fact that each of the members 7 carries an upstanding guide 18 at its left-hand end, which likewise moves in and out with the members 7 and functions with the chain 10 and member 13 in positioning the records of different sizes, one of these members 18 being shown to be pivoted, for a purpose hereinafter described.

Attention is also directed to the fact that improved adjustable feeding mechanism is provided adapted to cooperate with records of different size and also to be adjusted with the member 15 heretofore described. This feeding mechanism being later more fully described, it is sufficient here to state that it includes spaced rotatable wheels 89 also movable bodily within the limits of longitudinal slots 90 in the member 6 as the member 15 is moved with the member 14, and that these wheels are adapted to feed the records laterally onto the table 2 (Fig. 2) after their release from the magazine, while their movement with the member 15 is such as to adapt the wheels 89 to cooperate with records of different size. Herein, the member 15 is operatively connected to this record feeding mechanism by a substantially V-shaped member 15^c. This, in turn, has its arms connected to part 92 and slidable through the casting 5 to accommodate records of different size, and its opposite end is so connected to the member 15 by resting in a slot 15^d therein, that the wheels are moved back one inch when the member 15 is moved two inches, while nuts 15^e on the ends of the member 15^c engage the casting 5 to position the parts. Thus it will be noted that the feeding mechanism is also enabled to cooperate with records of different size and automatically adjusted when the member 15 is adjusted, as above described.

Associated with the size adjusting mechanisms described is also improved means for automatically adjusting the throw or swing of a sound arm 3^a, which carries the sound box 3, in order that the same may cooperate with records of dif-

10 different diameter. Herein, a variation in swing of the sound arm 3^a about its axis 23 is effected by automatic means connected to the adjustable guides 7, and more particularly to the pin 8 which 5 is disposed adjacent the sound arm 3^a when the latter is in its outermost position. Here, it will be noted that a generally triangular shaped stop member 24 having an abutment 25 at one of its ends and pivoted as a whole at 26 to the under 10 side of the base 6, is provided with a slot 27 in its other end which is adapted to receive the pin 8. Consequently, when the guide 7 is adjusted for a smaller record the projecting end 25 of the member 24 will limit the swing by being swung across 15 the end of an arcuate slot 28 formed in the base 6 and itself forming a passageway for a pin or arm 29 (Figures 6 and 11) depending from the sound arm 3^a at a point between its ends (Figs. 1 and 3), while when the guide is adjusted for a 20 larger record the end 25 will be swung away to permit the desired longer swing of the reproducer. Thus it will be observed that when through the mechanism heretofore described the guides 7 are 25 adjusted, the right-hand pin 8 on the upper guide 7 shown in Fig. 1 actuates the member 24 in such manner as automatically to shorten the length of swing of the sound arm 3^a when a 10-inch record is to be played or reproduced, or automatically to 30 lengthen the swing of that arm when a 12-inch record is to be played or reproduced.

Operatively connected with the mechanisms heretofore described is also an improved setting and indicating mechanism so connected as to be adapted, upon the operation of a single conveniently operable control member, to move each 35 of the members 7, 13, 89 and 25 to adjust them simultaneously for records of different size, and also to serve as an indicating means indicating the record size for which the machine is adjusted 40 at any time. Herein this controlling mechanism includes a rotatable control member 19 which, as shown in Fig. 2, is suitably journaled on the top of the base 6 at one side, and herein to the left, of the member 14. This member 19 herein 45 carries an indicator 20 and a knob 21 whereby the indicator may be rotated, herein from one position opposite an indication "10" to another indication "12", these numerals being suitably fixed to the top of the base 6 and indicating the different predetermined record sizes. Herein the member 19 is also pivotally connected to a downwardly extending rod 22 under the base 6, which, as shown in Fig. 2, extends to the right from the member 19 to the front end of the member 15 50 previously mentioned. Thus, it is made possible by simply turning the pointer 20 on the member 19 from a position opposite the numeral "10" to a position opposite the numeral "12", to make all the required adjustments of the members 7, 13, 55 89 and 25 to adapt the machine for twelve-inch records as distinguished from ten-inch records, or vice versa, while a glance at the indicator 20 will disclose the record size for which these parts are adjusted at any given time.

60 Assuming that the machine has been adjusted to operate on records of the desired size, let us next consider how a record is inserted in the magazine comprising the chain 10 and members 14, 13 and 18. Here it will be noted that the chain 65 10 presents a plurality of laterally extending vertically spaced record supports on its left-hand side (see Fig. 2), ten such supports 30 being there provided between the sprocket 11 and member 12 and one being carried on each chain link. Thus, 70 if desired, an operator wishing to fill the maga-

75 zine may swing down the member 18 (Figs. 1 and 2), i. e. move it from the full-line to the dotted-line position shown in Fig. 2, and then insert ten records from that side, with the bottommost record supported on the top of the member 13 and on the bottommost member 30, and each of the upper records supported at the left-hand side on the next lower record and at the right-hand side on the next higher member 30. Thus it will be evident that the magazine may be filled from the 10 side with any suitable number of records, ten being provided for in this illustrative construction and the records being supported in a generally horizontal superimposed relation at one side of the table. When the records have been thus inserted 15 from the side, the member 18 will, of course, be manually returned to its upright position.

In the preferred form, however, provision is made whereby the records may be inserted from the top, and the mechanism enabling this to be 20 done is utilized as a part of the control mechanism, as hereinafter described. Herein, in inserting a record from the top, one edge of each record is placed on its proper support 30 and the other edge thereof subsequently forced down in 25 such manner as to engage a hooked end or latch 31 on a member 32, disposed next and parallel to the member 14 and pivoted at 33 on that member. This swings the member 31 to the left about its pivot, as shown in Fig. 5 to compress a spring 34 30 acting between the lower end of the member 32 and a suitable depending extension 35 on the member 15, the spring herein being coiled about a rod 36 pivoted at 37 to the member 32 and suitably connected to the extension 35. Thus the 35 records may be inserted from the top, and when this occurs the latch 31 is operated by the insertion of each record, the latch being thrown back automatically as each record passes it and automatically returned to its initial position by the 40 spring 34.

Associated with this latch mechanism is improved actuating mechanism for a record counting mechanism. Herein, this actuating mechanism includes a horizontally disposed member 38 (Fig. 2) carried on the lower end of the member 32. As shown, this member 38 extends to the left from the bottom of the member 32 and is connected thereto between the same and a shorter upstanding supplementary member 39, the upper end of 50 which is connected to the member 32 by the pivot pin of the connection 37. In this construction, the vertically disposed left-hand end of a reciprocable counting member 40, disposed beneath the member 15, extends over and rests upon the member 38 between the members 32 and 39 and below the connection 37. When the member 32 is in upright position, the left-hand end of the member 38 also engages a flat surface 41 on the bottom of the member 40, while when the member 32 55 is rocked, the opposite end of the member 38 is adapted to engage a shoulder 42 on the member 40. Thus, each time that the latch 31 is swung back around its pivot, the member 40 is projected to the right to actuate suitable counting mechanism, hereinafter described, and, a plurality of surfaces 41 and shoulders 42 being provided in longitudinally spaced relation on the member 40, such an operation is made possible irrespective of the size of the record.

70 Considering next the counting mechanism actuated by the actuating mechanism therefor just described, it will also be noted that the member 40 is bent between its ends, as at 43, to provide a higher horizontal right-hand end portion there- 75

on. Herein, this portion is reciprocable through a suitable opening in an upright annular flange 44 on the main frame casting 5 supported on the motor frame 1 and supporting the base 6. Herein, this inner end of the member 40, when reciprocated to the right (Fig. 2), moves into engagement with projections or teeth 46 on a counting wheel 47 rotatable on a vertical axis on an adjacent surface of the casting 5. Thus, each time that the latch 31 is moved to the left in Fig. 2, the right-hand end of the member 40 is moved to the right into engagement with one of the teeth 46 on the counting member 47 in such manner as to rotate the member 47 one tooth and thus count the record. Further, it will be noted that a coiled spring 48 is connected between that end of the member 40 and the flange 44 in such manner as automatically to return the member 40 to the retracted position shown in Fig. 1, where-
in it does not interfere with the rotation of the member 47. It will also be noted that a spring pressed ball 49 seated in the casting 5 beneath the counting wheel 47 is also adapted to be seated successively in corresponding openings 50 in the under side of the counting wheel 47 so as to hold the latter in each position of adjustment thereof, these openings 50 herein being disposed entirely around the under side of the counting wheel.

Associated with the counting wheel is also improved indicating mechanism. Herein this mechanism assumes the form of a dial 51 having a knob 52 and journaled on the top of the base 6, this dial 51 also having a pointer 53 adapted to be moved opposite buttons respectively marked "10", "9", "8", "7", "6", "5", "4", "3", "2", "1", and "0". Further, the dial 51 is pivotally connected at 54 on the under side of the base 6 to a rod 55 which has teeth 56 on its inner edge engaging with cooperating teeth 57 smaller than the teeth 46, on a smaller mutilated gear 58 coaxial and rotatable with the counting wheel 47 and disposed in a plane above that wheel. Thus, whenever a record is inserted from the top in such manner as to actuate the latch 31 and counting wheel 47, the mutilated gear 58 is actuated to move the member 55 and, through the latter's connection with the dial 51, cause the indicator 53 on that dial to move from the operative position opposite "0" to one of the numbers "1" to "10" and thus count and indicate the number of records placed in the magazine.

This indicating mechanism also provides improved starting and stopping mechanism for the machine. Herein, it will be noted that it controls a main control wheel or cam 64 which in turn controls the operation of the record releasing, feeding, and other subsequently operated mechanisms hereinafter to be described. More particularly, this member 64 is rotatably mounted on suitable bearings, herein of the ball type, within the casting 5 and between the same and the base 6 on the same axis as the shaft 4 though radially spaced from the latter. It also is provided with gear teeth 65 on its periphery, which in turn mesh with a pinion 66 journaled and reciprocable as hereinafter described on an upright shaft 67 spaced substantially 90° around the member 64 from the wheel 47 (Figs. 1 and 11) and rotatable (Fig. 3) by means of operatively connected pulleys 68 and 69 from the motor shaft 4. As shown herein, this member 64 also carries on its periphery and inside the outer edge of the teeth 65 an upstanding lug 70 which is adapted to engage a plain or un-toothed portion

71 on the counting wheel 47 which overlies the teeth 65. Here, to avoid confusion, it should perhaps be said that the particular length of the un-toothed portion 71 of wheel 47 is unimportant and that only ten teeth are necessary. Thus, it will be noted that when the indicator 53 is opposite the button "0", the plain or un-toothed portion 71 of the member 47 is engaged by this lug 70 on the control wheel 64, thereby holding the latter against rotation, and since the clutch 118 is engaged, also holding the belt-connector motor against rotation, the parts then occupying the position shown in Figs. 1 and 9. However, when the indicator 53 is moved opposite the button "1" it will be observed that the un-toothed portion 71 is moved out of the path of the lug 70 so that the member 64 may rotate and start the machine in operation.

Considering this mechanism more particularly, it will also be noted that, since one revolution of the main control wheel 64 will advance the member 47 by one tooth, if the indicator 53 is moved opposite number "10" the member 64 will make ten complete revolutions, and with each revolution, through the connecting mechanism, cause the indicator 53 to move progressively downward to "0", the indicator reaching this position simultaneously with the engagement of the un-toothed part 71 with the lug 70. Thus it will be evident that when the mechanism including the dial 51 is moved to any of the positions "1" to "10", the machine controlling member 64 will be started and permitted to operate as many times as is necessary to play, or reproduce, the number of records indicated. Moreover, this member 64 will be stopped automatically as soon as the required number of records has been reproduced or whenever the indicator 53 is moved to "0", the interruption then occurring as soon as the lug 70 rotates into contact with part 71, i. e. at the end of the playing, or reproduction, of the last record. These means, through the improved operating connections described, may also function during the playing of a series of records, as indicating means, showing at a glance at the dial at any time how many more records are to be played or reproduced.

Assuming that the motor 1 is wound and that the parts are in the position shown in Fig. 1, with the cam wheel 64 ready to rotate when the tooth 70 thereon is released, it will be evident that when a record is inserted in the magazine from the top, i. e. by operating the latch 31, the control wheel 64 will begin to rotate so that the various other mechanisms, hereinafter described and operated in timed relation therewith, may also begin to operate to release the record from the magazine, feed the record to the table, cause the reproducer to engage therewith, etc. Thus, it will also be evident that when the motor is wound the machine will be automatically started following the first operation of the latch 31, i. e. by the mere insertion of a record in the machine. It will also continue to operate until, depending on the position of the indicator, determined by the number of records in the magazine or the adjustment by the operator for a lesser number of records, the un-toothed portion again engages the tooth 70. Obviously, when the records are inserted from the side, a manual movement of the indicator will be necessary from the "0" position to a position corresponding to the number of records it is desired to play.

Considering the various cooperating mechanisms referred to, and first referring to the record

releasing mechanism, it will be noted that improved mechanism is provided for this purpose. Herein, the control member 64 is provided on its upper surface with a short upstanding cam or track 72, which, when the machine is started from the "0" position shown in Fig. 1, immediately passes under a roller 73 on the inner end of a radially extending rocker member 74, herein arched near its inner end and pivoted at 75 on the casting 5 and extending radially therefrom. Thus, the outer end of this shaft is lowered, thereby extending a coiled spring 76 connected to the outer end thereof and also pulling down a vertically extending member 77 which controls the record releasing mechanism. More particularly, it will be noted that the end of the member 74 is pivoted at 78 to the lower end of this member 77, and that the upper end of the member 77 is vertically slidable within the limits of a slot 79 on a pin 80 carried on the outer end of a shaft 81 carrying the sprocket 11 of the chain 10, the shaft 81 herein being journaled in a suitable tubular member 82, which is in turn supported on a bracket 83 carried on the casing 6 just outside the limits of movement of the topmost guide 7 shown in Fig. 1. Moreover, it will be noted that the member 77 is provided on its upper end with vertically spaced lugs 84 and 85 adapted to cooperate with teeth 86, herein five in number, on a toothed wheel 87 rotatable with the sprocket 11, which also has five teeth. Thus it will be evident that when the cam 72 operates the rocker member 74, the member 77 will be pulled downward in such manner as to pull the lug 85 out of the path of one of the teeth 86 and cause the lug 84 to contact with an adjacent tooth 86, and thereby, since both the member 87 and sprocket 11 are provided with the same number of teeth, herein five, enable the sprocket 11 and shaft 81 to be rotated in a counter-clockwise direction by the weight of the record or records through a distance equivalent to one tooth. Hence, the bottom record support 30 of the chain 10 will move downward to effect the separation of the bottommost record which is supported at opposite edges on the bottommost laterally projecting support 30 on the chain 10 and on the top of the member 13. Obviously, after the member 73 has passed over the cam 72, the spring 76 will also return the member 77 to its initial position ready to discharge another record when the parts 73 and 72 again engage on the next revolution of the member 64. As a result, the total movement of the wheel 87 is one tooth.

Upon separation of the bottommost record from the other records in the magazine, the record is fed laterally onto the table 2 by improved lateral feeding mechanism. More particularly, when the chain supported edge of the bottommost record is lowered by the lowering of its support 30, it will be evident (Fig. 2) that that edge of the record will fall toward the table 2 and be pushed down by the next upper support 30 in the event of sticking, in such manner as to cause its opposite rounded edge to pull out laterally from between the top or supporting part of the rounded supporting surface of member 13 and the next record next above, the downward slope on the surface of member 13 below the top thereof being such as to facilitate this movement while directing the record laterally toward the table. Further, the left-hand side of the record (Fig. 2) will strike the upper edge of an upstanding rest 88 in front of the member 13, this rest herein being long and narrow, as shown, and formed of yield-

ing or resilient material, as for example rubber or the like, while the right-hand portion of the record will fall upon a plurality of laterally spaced rubber faced wheels 89 extending up through suitable longitudinal slots 90 in the base 6. These wheels herein serve to feed the record laterally to the right in Fig. 2 over the table 2 and, in co-operation with the guide 7, center it on the table centering pin 91. Considering the mechanism more specifically, it will be noted that the wheels 89 are carried on a shaft 92, which is in turn carried in brackets 93 pivotally mounted at 94 on the under side and carried by members 15. Moreover, the shaft 92 carries at a point between its ends a coaxial worm gear 95, which in turn constantly engages with a worm 96 carried on a bracket member 97 likewise movable about the axis 94. Further, it will be noted that the worm 96 is carried on one end of a shaft 98, and that this shaft carries on the opposite end thereof a rubber tired wheel 99, while the member 97 carries a weight 100 normally biasing the wheel 99 against engagement with the table.

Thus, when a record falls on the wheels 89, the weight of the record causes the latter wheels to be depressed in such manner as to bring the wheel 99 into engagement with the under side of the rotating table 2 at a point between the pin 91 and the bracket pivot 94. Consequently, the rotation of the table is transmitted to the wheel 99, shaft 98, worm 96, worm gear 95, shaft 92, and wheels 89, in such manner and in such a direction as, due to the engagement of these wheels with the under side of the record, to cause the record to be fed laterally to the right and over the table by the wheels 89. Furthermore, it will be noted that by making the pin 91 of flexible, or resilient, material it may be made possible for these wheels 89 to continue to push the record across the table using the pin for a support, until the usual hole in the center of the record is above the pin, without damage to the record. Here it will be noted that the record during this lateral feeding movement is guided by the guides 7. Attention is also directed to the fact that the front edge of the record is held up by the wheels 89 so that the front edge of the record clears the pin 91 until it has passed over it. Further, when the record has been moved by the wheels 89 far enough to the right to overbalance, the right hand side of the record rests on the pin 91 and continues to be supported by it until the hole in the record comes over the pin 91, whereupon the record falls into place on the table, the same being then out of engagement with the wheels 89 and the weight 100 also lowering the wheel 99 from its driving position shown in Fig. 2.

When the record has been thus placed in centered position upon the table 2, improved reproducer controlling mechanism is next automatically operated. Here it will be understood that the sound box 3 is in the laterally displaced position shown in Figs. 1 and 2 when the record is placed on the table. It will also be noted that the sound box 3 is pivoted at 102 to the swinging sound arm 3^a so that the sound box may be raised and lowered about this pivot. A rearwardly extending arm 104 is also provided on the sound box and in turn connected at its outer end to a vertical link 105, which is in turn also connected to a lever 106 parallel to the member 104 and pivoted at 107 on the frame and also carrying a roller 108 on its inner end engageable with a raised cam track 109 on the member 64. This track 109 is continuous except for an opening 110, and is out-

side the track 72 and near the outer periphery of the member 64. As a result, when the sound arm 3^a is swung to the position shown in Fig. 1, the sound box 3 is held in the elevated position shown in full lines in Fig. 3 while the cam 109 rotates and until after the record has been deposited on the table. When the record has been deposited upon table 2, the opening 110 in the cam 109 is disposed below the roller 108 and the roller drops into the same thereby causing the outer end of member 106 to be raised which, through connecting linkage with member 104, gently lowers the sound box 3 upon the surface of the record. The sound box 3 is then pushed over the surface of the record into engagement with the first or outer playing or reproducing groove of the record by means of a spring 111, carried on the base 6 and acting on a suitable depending member 112 carried by the arm 3^a.

Cooperating with this mechanism is also improved mechanism adapted to control the rotation of the main control wheel 64. Herein it will be noted that another cam surface 113 is provided on the latter just outside the cam track 109, and that this cam surface 113 is also continuous save for an opening 114 which comes into operative position very shortly after the opening 110. More particularly, this opening 114 then comes under a roller 115 carried on a rocking member 116 pivoted at 117 on the frame and carrying between the roller and the pivot a reciprocable clutch member 118, rotatable with the pinion 66 on the shaft 67 and adapted to engage when raised, with a cooperating clutch member 119 secured to shaft 67 to rotate therewith. In this construction the roller 115 is normally so held up by the cam 113 that the clutch 118, 119 is not permitted to disengage, disengagement only taking place when the roller 115 drops into the opening 114. However, when this occurs, the clutch is disconnected and the rotation of the member 64 is stopped so that the sound box 3 may operate to reproduce the record in a usual manner, the sound arm 3^a swinging about its axis during this operation.

Cooperating with the mechanism is also improved mechanism controlled by movement of the sound arm for again connecting the clutch after the record has been reproduced. More specifically, it will be noted that as this rocking member 116 is moved about its pivot 117, the outer end thereof is raised, and that this outer end carries an inclined member 120 connected to a part of the frame by a spring 121 and disposed in the path of the pin or arm 29. Thus, when the record has been reproduced, the pin 29, striking this inclined surface, acts to depress the outer end of the member 116 and accordingly raise its inner end and reconnect the clutch 118, 119, whereby member 64 will start rotating, and at the same time roller 115 will be raised out of the opening 114 in the cam 113.

Here, improved mechanism is also provided to return the sound arm 3^a and sound box 3 from the lowered innermost position thereof occupied when the record is finished to the raised laterally swung starting position thereof indicated in full lines in Fig. 1. The raising of the sound box 3 is effected by the cam 109 and the connected linkage, the inner end of the arm 106 being raised shortly after the member 64 resumes its rotation and through the linkage pulling down the member 104 to raise the sound box from the record. Further, it will be noted that a depending arm 122 under the pivot of the member 106 is pivotally

connected at 123 to an outwardly extending link 124, which is in turn connected through a coiled spring 125 to the lower end of the depending member 112 on the sound arm 3^a. Thus, after the sound box 3 has been raised, the whole arm 3^a is swung from its innermost position, occupied when the record is completed, to its outermost position shown in Fig. 1, ready to play a new record, the amount of swing being determined by the size of the record, as heretofore described.

Cooperating with this mechanism, and likewise actuated from the member 64, when again set in motion, is improved mechanism for discharging the record. Herein it will be noted that the member 64 carries still another cam track 130 inside the cam track 109 and between the same and the cam track 72, this track 130 being substantially longer than the track 72 but shorter than the other tracks. When the record has been reproduced and after the sound box has been raised, the mechanism is so timed as to bring this cam track under a roller 131, substantially diametrically opposite the roller 108 and pivoted on a rocker member 132, which is in turn pivoted at 133 on a depending portion on the base 6. This rocker member 132 herein also carries at a point between its ends an upstanding member 134 carrying a roller 135, the construction being such that when the member 132 is rocked the roller 135 is raised into engagement with the edge of the record which protrudes laterally beyond the table. As a result, the roller 135 lifts up this edge of the rotating record from the table 2 in such manner as to cause the record to clear the centering pin 91, as shown in Fig. 3, while still being supported at its opposite side on the rotating table. Because of the rotation of the table, the record is accordingly fed forward, or to the right in Fig. 1, and off of the table while the table keeps the record spinning. Further, it will be noted that this elevation of one side of the record causes it to clear an abutment 101, which is located on the elevated side of the record, and that the rotating table further causes the record to be discharged while spinning against the vertical portion of the adjacent guide 7 and a suitable padded abutment 136 spaced from the abutment 101 and on the far side of a record discharge chute 137. Striking this abutment 136, the outward movement of the record is stopped, and the outer end of the same then drops down into a suitable record compartment 138, following a suitably inclined surface 139 which forms a chute leading it away to a suitable receptacle.

Should it be desired to discontinue the playing of any record, improved mechanism is provided whereby this may be done. This mechanism herein assumes the form of a rejector button 143 operable from the top of the base 6 at a point adjacent the sound arm and depressible through the base into engagement with the rocking lever 116, a suitable extension 144 being provided on the rock lever so that the latter may be moved about its pivot whenever the button is depressed. Thus the roller 115 may be raised out of engagement with the opening 114 in the cam 113 and thereby, through starting the member 64 prior to the completion of the record, cause the automatic mechanism heretofore described to operate to discharge the selected record. This mechanism may obviously be operated during the playing of any record.

Attention is also directed to the fact that improved mechanism is also provided whereby, even if the indicator 53 is moved from "0" opposite

one of the numbers "1" to "10" when no records are in the machine, the machine will automatically be returned to starting position so that it is always ready for operation. More particularly, it will be noted that when the machine is thus improperly started without any record therein, the sound box 3, instead of coming into engagement with the outer edge of a record, is enabled to drop down below the surface of the turntable, as shown in dotted lines in Fig. 3. This brings a lug 145 carried on the arm 106 into contact with the under surface of the arm 116 in such manner as to hold that arm up and thereby hold the clutch 118, 119 engaged by the weight of the connected reproducer mechanism. Hence, with the parts held in this position when the roller 115 passes over the opening 114 in the cam track 113, the clutch will not be disengaged as heretofore in such manner as to discontinue the rotation of the member 64, and the latter will accordingly be enabled to continue to rotate, this rotation being similarly continued a sufficient number of times to bring the mechanism back to its "0" position.

Obviously, after the first record has been thus discharged, the mechanism will be free automatically to release and feed another record to the table and reproduce the same and as many other records as may be in the magazine, all of the mechanisms being thereafter controlled and operated in the desired sequence heretofore described. In practice the mechanism is so timed that the whole sequence of operations including the discharge of one record and the substitution of another is so expeditiously carried out that there is an interval of only approximately forty seconds between the completion of one record and the beginning of another. More particularly, it will be noted that the main control member 64 is so arranged that it makes a complete revolution during this interval, and during this revolution automatically operates the various mechanisms in the desired sequence.

Considering the operation more specifically, it will be evident that by a suitable adjustment of the indicator 20 the machine may be adapted to use for records of different size. If desired, the machine may then be used as a single record phonograph, i. e. one adapted to play and discharge a single record. To accomplish this, the selected record may be placed in the machine by merely placing it in the magazine from the top, in which case the machine is started automatically and continues to operate to reproduce and discharge the record, the indicator then coming back to "0". The record may also be inserted from the side, or even placed manually directly on the table, as in an ordinary single record, non-automatic machine. In either case, the indicator 53 is thereafter manually moved from "0" into position "1", whereupon the record will be automatically played and discharged and the machine automatically stopped, ready for another record. However the record reaches the table, the lug 70 is so located that the machine always stops with the reproducer laterally swung and elevated and all the mechanism again in starting position, as illustrated in Fig. 1. When it is desired to reproduce a plurality of records, they may be similarly inserted either from the top or the side of the magazine, as heretofore described. When they are inserted from the top, the machine is automatically started, while when they are inserted from the side, it is necessary for the indicator 53 to be adjusted manually. In either

case, moreover, the indicator may obviously be adjusted, if desired, at any time in such manner as to call for the reproduction of only the bottom-most record or any number less than the whole number of records then in the magazine. If with the indicator opposite any selected number determined by the counting mechanism or the operator, the automatic mechanism is continued upon the reproduction of a series of records, it will obviously continue to function automatically, first to release the record from the magazine, then to feed it laterally onto the table and center it, then to move the sound box down onto the record, and then, after the reproduction of the record, to move the sound box back to starting position and discharge the record, whereupon the whole sequence of operations will begin over again and be repeated as many times as the position of the starting dial calls for, while the machine when it stops will always be ready for operation. If at any time the operator wishes to stop the machine, turning the indicator to "0" will cause this to occur after the reproduction of the record then being reproduced is completed. At any time during the reproduction of any given record, if the operator wishes, the reproduction of that record may also be discontinued at once by simply depressing the rejector 143, whereupon the record then being played is discharged and the mechanism proceeds to the reproduction of the next record, unless stopped by swinging the indicator to "0". Attention is also directed to the fact that additional records may be placed in the magazine while the machine is operating, and that the machine will continue to operate until the last of these is played, the mechanism being adjusted by the member 51 after the records are inserted from the side and being automatically adjusted by the member 31 during the insertion of records from the top. Obviously, with either type of insertion, automatic reproduction may be continued indefinitely as the magazine is emptied and refilled, without requiring any further attention on the part of the operator than the insertion of the records from the side and the adjustment of the member 51, or in the case of insertion from the top, the mere insertion of the records. The automatic return of the several parts to starting position after each predetermined operation also insures that the mechanism is ready to be restarted upon the insertion of another record. Moreover, it will be evident that if desired records may be removed from the magazine or changed in position therein while the machine is operating and without disturbing the operation of the latter, these removals or changes being readily effected from the side of the magazine. When a record is thus removed from one of the supports 30 in such manner as to provide a gap in the records in the magazine, it will also be noted that the mechanism continues to operate automatically in such manner that the automatic reproduction of the record on the next higher support 30 above the gap is not only effected but expedited in such manner as to shorten the silent period between the reproduction of the records before and after the gap. More particularly, the movement of the reproducer below the table when there is no record on the latter, results in maintaining the connection of the clutch, and this, in turn, results in eliminating the playing period when the clutch is ordinarily disconnected and thereby shortens this silent period. Attention is further directed to the fact that the entire mechanism is equally 75

well adapted to operate on large or small records despite the different problems presented due to the difference in the distances between the axes of the same in the magazine and the table axis, 5 the need for adjusting the initial record engaging position of the reproducer, etc. It will also be noted that the mechanism is adjustable to enable it to operate automatically on records of either diameter, all of the various mechanisms and 10 their controlling means being suitably adjusted by the adjustment of a single controlling means, which herein is manually adjustable.

As a result of my invention it will also be noted that the mechanism provided is exceedingly flexible so that it is adapted not only to meet the demand for an ordinary single record phonograph provided with automatic discharging and stopping mechanism, but also to enable great simplicity in operation and great flexibility of control when used as an automatic machine. Further, it will be observed that the mechanisms are such that the device is substantially "fool-proof", difficulties ordinarily arising from tampering with the machine or improper operation thereof being 20 in large part obviated. Attention is also directed to the automatic starting feature and to the concentration of the control in the two control dials and rejector member. The improved starting and stopping and indicating mechanism particularly provides an exceedingly convenient and satisfactory control means giving great flexibility of control at the same time that through its connections it prevents damage to the machine through improper operation. It will also be noted 30 that the mechanism itself is of an exceedingly simple character and of a type enabling the whole machine to be produced very economically. These and other advantages of my improved construction will, however, be clearly apparent to those skilled in the art.

While I have in this application specifically described one embodiment which my invention may assume in practice, it will be understood that the same may be modified and embodied in various other forms without departing from its spirit or 45 the scope of the appended claims.

What I claim as new and desire to secure by Letters Patent is:

1. In a phonograph, mechanism for reproducing a record including record receiving means, and mechanism for controlling said reproducing mechanism to effect automatic reproduction of a record having means for automatically setting said reproducing mechanism in operation to reproduce the deposited record upon the deposit of but a single record on said receiving means.

2. In a phonograph, mechanism for reproducing a record including a record support and means other than said support and actuated while said support is stationary and by a record deposited thereon for automatically effecting reproduction of the record upon the deposit of but a single record on said support.

3. In a phonograph, mechanism for reproducing and discharging a record including record receiving means, and means for automatically effecting the reproduction and discharge of the record automatically set in operation upon the insertion of but a single record in said receiving means.

4. In a phonograph, mechanism for reproducing and discharging a record including record receiving means, and means for automatically starting said mechanism upon the insertion of but a single record in said receiving means and auto-

matically stopping said mechanism upon the discharge of that record.

5. In a phonograph, mechanism for reproducing a record including record receiving means, and mechanism automatically set in operation upon the deposit of a record on said receiving means and automatically controlling said reproducing mechanism to effect the reproduction of that record having controlling means movable relative to said receiving means and projecting into the path of a record inserted thereon.

6. In a phonograph, mechanism for automatically reproducing a record including record receiving means, and mechanism automatically operative when only one record is inserted on said receiving means to control said mechanism to effect the automatic reproduction of that record having controlling means actuated by the insertion of said record on said receiving means and means for automatically removing said reproducer mechanism from said record when reproduced and returning said mechanism to starting position.

7. In a phonograph, a record support, automatic reproducing mechanism for reproducing records therein, and controlling mechanism for said automatic mechanism having controlling means disposed above and movable relative to said support by a record being placed thereon and operative connections controlled by said means for effecting automatic reproduction of said record.

8. In a phonograph, co-operating record delivery and reproducing mechanism including a record support adapted to receive a record, and mechanism for setting said mechanisms successively in operation upon the insertion of a record on said support to deliver and reproduce said record having a controlling member movable relative to said support and engaged and actuated by the inserted record.

9. In a phonograph, mechanism for automatically reproducing a series of records having a magazine adapted to receive records, and mechanism for automatically starting said reproducing mechanism in operation upon the insertion of the first record in said magazine and continuing said first mentioned mechanism in operation to reproduce said record and any record subsequently inserted in said magazine while any previously inserted record is in said magazine or being reproduced.

10. In a phonograph, mechanism for automatically reproducing a series of records having a magazine, and means for automatically starting said mechanism in operation upon the insertion in said magazine of the first record of a series inserted therein in the same filling operation controlling said first mentioned mechanism to effect the reproduction of said first record and of the subsequently inserted records in said series in succession after reproduction of said first record.

11. In a phonograph, mechanism for automatically feeding and reproducing a record including a magazine having means for receiving a new record while a record in said magazine is being fed therefrom by said feeding mechanism, and means including a control member automatically actuated upon the deposit of a record in said magazine when said mechanism is empty for starting said mechanism and effecting the successive automatic feeding and reproduction of that record and of any additional records in-

serted in said magazine prior to the completion of reproduction of the last record therein.

12. In a phonograph, mechanism for automatically feeding and reproducing a record including a magazine, means automatically operative when only one record is deposited in the magazine to set said mechanism to start successively the automatic feeding and reproduction of that record, and means automatically operative upon each operation of said mechanism for returning its feeding mechanism into record receiving relation to said magazine and moving its reproducer mechanism from the reproduced record into an initial position ready to operate on a new record.

13. In a phonograph, mechanism for reproducing a record having a magazine, and controlling means for said mechanism actuated upon the insertion of records in said magazine operative automatically to reproduce one or more records and also automatically operative to effect successive automatic reproduction after the reproduction of said records of one or more added records inserted while one or more original records still remain in said magazine.

14. In a phonograph, a record rotating table, mechanism for automatically reproducing a series of records on said table having a record support adapted to be refilled while said mechanism operates, and controlling mechanism for said first mentioned mechanism for effecting automatic reproduction of the first record placed on said support and all subsequent added records and having controlling means movable relative to said support and projecting into the path of a record placed thereon.

15. In a phonograph, a record rotating table, a constantly open record magazine, and mechanism for automatically reproducing on said table a record inserted in said magazine including a starting member projecting into the path of the first record being disposed in said magazine and deflected laterally by said record, and co-operating controlling mechanism for said automatic mechanism automatically starting the same upon operation of said member and automatically stopping said mechanism upon reproduction of said record.

16. In a phonograph, mechanism for automatically reproducing and discharging a series of records having a magazine, and controlling means for said mechanism automatically set in operation upon the insertion of the first record in said magazine and operative automatically to control the mechanism to effect the successive reproduction and discharge of all records inserted in said magazine.

17. In a phonograph, a record rotating table, a record magazine, cooperating record feeding, reproducing, and discharging mechanisms, and control mechanism actuated upon the insertion of a record in the magazine and controlling said mechanisms to effect successive automatic feeding, reproduction and discharge of said record.

18. In a phonograph, a record rotating table, a record magazine, mechanism for reproducing a series of records, and controlling mechanism therefor operative to reproduce automatically all records in said magazine on said table and including an automatically operated starting and stopping mechanism having a controlling member projecting into the path of a record being deposited in said magazine and actuated by said record while said magazine is stationary.

19. In a phonograph, a record rotating table, reproducer mechanism movable transversely above a record on said table, a record magazine, and mechanism set in operation by the insertion of records in said magazine and controlling said reproducer mechanism and having a plurality of relatively movable means, one for supplying records in said magazine to and the other for discharging them from said table, and operative, respectively, prior to and after each reproduction.

20. In a phonograph, mechanism for feeding and reproducing a series of records including a magazine adapted to be refilled while said mechanism operates, a laterally offset record rotating table disposed in planes spaced below said magazine and rotatable on a stationary axis, and means for feeding records laterally relative to and below said magazine into centered position on said table, and means automatically controlled by the inserted records operative to effect automatic reproduction of all records first placed in said magazine and automatically operative upon refilling the latter while certain records remain in the magazine to effect automatic reproduction of the added records after said remaining records.

21. In a phonograph, a record rotating table, record supporting means supporting records substantially horizontally at one side of the table, record feeding means successively separating the bottommost record therefrom and feeding it laterally onto the table, reproducer mechanism successively acting on records on the table, means other than said feeding means for discharging the reproduced records laterally from the table and manually actuatable means for automatically setting said feeding means, reproducer mechanism, and discharging means to act automatically on all or any selected part of the records supported in said support.

22. In a phonograph, mechanism for automatically feeding, reproducing and discharging a series of records including a magazine and having means for enabling records to be added to the records in said magazine after certain of said records have been reproduced, in position for reproduction after the remaining records without removing the remaining records in the magazine and at any time while the mechanism is operating, and controlling means for effecting successive feeding, reproduction and discharge of all the records originally in the magazine and successive feeding, reproduction and discharge of all added records after the original records are reproduced and then stopping said mechanism.

23. In a phonograph, automatic record reproducing mechanism having record receiving and feeding means adapted to receive additional records while feeding records for reproduction, and controlling mechanism for said reproducing mechanism having a co-operating control member movable at will to initiate automatic reproduction of records originally in said receiving means and subsequently adjustable while continuing automatic reproduction to effect automatic reproduction of added records.

24. In a phonograph, automatic record reproducing mechanism having record receiving means, and controlling mechanism for said reproducing mechanism having a co-operating control member controlling the starting and stopping of said reproducing mechanism, and means for automatically moving said member to starting position upon the deposit of the first record on said receiving means and automatically moving said

member to stopping position when said record is reproduced.

25. In a phonograph, automatic record reproducing mechanism having record receiving and feeding means adapted to receive additional records while feeding records for reproduction, and controlling mechanism for said reproducing mechanism having a co-operating control member manually movable to start automatic reproduction of a predetermined number of records 10 and also subsequently manually adjustable while continuing said automatic reproduction to effect automatic reproduction of a number of records more or less than said predetermined number of records.

15 26. In a phonograph, mechanism for automatically reproducing a series of records having record receiving means, and controlling mechanism for said reproducing mechanism including record counting means automatically adjustable as records are inserted in said receiving means and manually adjustable to set said first mentioned mechanism to effect automatic reproduction of any predetermined number less than the total 20 of the series therein.

25 27. In a phonograph, mechanism for automatically reproducing a series of records having record receiving means, and controlling mechanism for said mechanism including a control member and cooperating controlling means, said member being automatically adjustable as records are inserted in said receiving means to control said controlling means to effect automatic reproduction of said records and also manually adjustable to control said controlling means to effect automatic reproduction of any number 30 less than the total in said receiving means.

35 28. In a phonograph, a record magazine comprising a record support adapted to receive a plurality of records therein, record reproducing mechanism, means operable automatically as each record is being separately deposited in said magazine for counting the records inserted therein, and means controlled by said last mentioned means for effecting reproduction of said 40 records by said reproducing mechanism.

45 29. In an automatic phonograph, automatic mechanism for reproducing a series of records having a magazine, and control mechanism for said mechanism including a control member automatically adjusted as each record is inserted 50 in the magazine of said first mentioned mechanism to provide for reproduction of the record and also manually adjustable to reduce the number of records reproduced.

55 30. In an automatic phonograph, automatic mechanism for reproducing a series of records having a magazine, and control mechanism for said mechanism including a control member and means for automatically adjusting the same as each record is inserted in the magazine of 60 said first mentioned mechanism and also automatically adjusting said member as each record is reproduced.

65 31. In a phonograph, a record rotating table, a record magazine, co-operating record feeding and reproducing mechanisms, and controlling mechanism for said mechanisms for effecting automatic feeding and reproduction of a series 70 of records including a dial and a control member and means for adjusting one of the same automatically as records are inserted in said magazine.

75 32. In a phonograph, a record rotating table, a record magazine, co-operating record repro-

ducing mechanism, and controlling mechanism therefor for automatically reproducing a series of records from said magazine on said table including indicating means and a control member and having one of the latter automatically adjusted relative to the other as each record is inserted in said magazine and after each record is reproduced and manually movable to stopping position at any time during reproduction.

80 33. In a phonograph, a record magazine, a record rotating table, co-operating record reproducing mechanism, and controlling mechanism therefor for effecting automatic reproduction of a series of records in said magazine including an indicator and a co-operating control 15 member, one of the same being automatically adjusted as each record is inserted in said magazine or reproduced by said reproducing mechanism and also manually adjustable at any time to vary the number of automatic reproductions.

85 34. In a phonograph, a record magazine, a record rotating table, co-operating record reproducing mechanism, and controlling mechanism therefor for effecting automatic reproduction of a series of records in said magazine including an 20 indicator and a co-operating control member, the latter being automatically adjusted in opposite directions as each record is inserted in said magazine or reproduced by said reproducing mechanism and also manually adjustable in 25 either direction at any time to increase or decrease the number of automatic reproductions.

90 35. In a phonograph, automatic record reproducing mechanism having record receiving means, and controlling mechanism therefor operative successively to reproduce a series of records deposited in said receiving means and including a control member automatically movable progressively in opposite directions as successive records are reproduced by said reproducing mechanism or deposited in said receiving means and manually adjustable to vary the number 35 of automatic operations at will.

95 36. In a phonograph, automatic record reproducing mechanism having record receiving and feeding means adapted to receive additional records while feeding records therein for reproduction, and controlling mechanism therefor operative to reproduce a series of records including a member manually movable to starting position to effect automatic reproduction of records in said receiving means and to a new starting position to effect automatic reproduction of added records while continuing successive reproduction and means for automatically moving said member toward stopping position as successive records are reproduced.

100 37. In a phonograph, mechanism for automatically reproducing a series of records including a magazine permitting record changes during reproduction, a reproducer, a record rotating table, and means for discharging a reproduced record from the latter, and controlling mechanism for said mechanism including a control member adjustable manually at any time during reproduction to decrease or increase at will the number of predetermined automatic operations of said automatic mechanism.

105 38. In a phonograph, a record magazine, a record rotating table, cooperating record reproducing mechanism, and controlling mechanism therefor for automatically reproducing a series of records in said magazine on said table including a dial and a control member and having one of the latter automatically adjusted relative to the other 70

- as each record is inserted in said magazine or reproduced by said first mentioned mechanism.
39. In a phonograph, automatic record reproducing mechanism including a magazine adapted to receive records in a plurality of ways, and controlling mechanism for said mechanism including a control member only movable automatically upon the insertion of a record in said magazine in one manner and also manually adjustable to accord with the number of records in said magazine.
40. In a phonograph, automatic reproducing and discharging mechanism including a magazine adapted, while continuing operation of said mechanism, to receive records in addition to any records remaining in said magazine and without removal of the latter records, and controlling means manually adjustable to set said first mentioned mechanism to effect successive automatic reproduction and discharge from said first mentioned mechanism of all the records first inserted in said magazine and also manually adjustable while continuing operation to reset said first mentioned mechanism to effect automatic reproduction and discharge from said mechanism of the added records.
41. In a phonograph, automatic reproducing mechanism including a magazine adapted to permit the substitution of new records for those in said magazine or, without removing the records in the magazine, the addition of other records for reproduction after those records already in the magazine without interrupting successive reproduction, a rotating table, mechanism for discharging a record therefrom, and controlling means for at will successively setting and resetting said automatic reproducing and discharging mechanisms to automatically reproduce on said table and discharge therefrom various predetermined numbers of records successively inserted in said magazine.
42. In a phonograph, mechanism for effecting successive automatic reproduction and discharge of a predetermined number of records including a magazine having means for receiving additional records while continuing reproduction, a record rotating table, means for successively reproducing on and discharging from said table records in said magazine, and controlling mechanism having a controlling member manually adjustable at will to increase the number of successive automatic operations indefinitely to correspond with additional records inserted in said magazine.
43. In a phonograph, mechanism for reproducing a record having record receiving means and set in operation by the insertion of a record in said receiving means and including a plurality of devices requiring adjustment for different sized records, and controlling means for said mechanism including a single control member movable to make the various adjustments of said devices to adapt the mechanism to operate upon records of different size.
44. In a phonograph, mechanism for reproducing a series of records, and controlling mechanism therefor having means automatically set as records are inserted in said mechanism to effect automatic reproduction of all inserted records and means manually adjustable to set the machine to effect automatic playing of one of the records therein or more of said records in a series of full length or such shorter length as the operator desires.
45. In a phonograph, mechanism for reproducing a series of records having record receiving means, and controlling mechanism for said re-
- producing mechanism manually operable when said reproducing mechanism is in starting position to set the latter to effect an automatic substituting operation independently of the presence of records therein and the automatic return of said mechanism to starting position.
46. In a phonograph, mechanism for reproducing a series of records having a record magazine, and controlling mechanism for said mechanism for effecting automatic operation thereof automatically adjustable by the insertion of records in said magazine to set said reproducing mechanism to go through a predetermined number of automatic operations and also manually adjustable to set the latter for any lesser number of predetermined automatic reproducing operations.
47. In a phonograph, mechanism for reproducing a series of records, and controlling mechanism therefor for effecting automatic operation thereof including a manually operable starting member normally engaged and operated by an inserted record and operable when said reproducing mechanism is in starting position, and means for automatically returning said first mentioned mechanism and said member to starting position whether records are in said mechanism or not when said starting member is operated.
48. In a phonograph, mechanism for reproducing a series of records, and controlling mechanism for effecting automatic operation thereof and operable when said reproducing mechanism is in starting position to set said reproducing mechanism to go through one or more automatic operations and automatically return said reproducing mechanism to starting position whether there are sufficient records therein to correspond to the selected number of operations or not when said controlling mechanism is operated.
49. In a phonograph, a rotating table, co-operating record reproducing and discharging mechanisms, and controlling mechanism therefor including cam means rotatable about the axis of said table and controlling the operation of each of said first mentioned mechanisms.
50. In a phonograph, a constantly rotating table, record supplying, reproducing and discharging mechanisms cooperating therewith, and controlling mechanism including a single rotating cam wheel controlled by said reproducing mechanism and controlling said first mentioned mechanisms and likewise having means cooperating with said reproducing mechanism for connecting or disconnecting said cam and said table to control the simultaneous rotation thereof.
51. In a phonograph, a record rotating table, mechanism for reproducing and discharging a record thereon, and controlling mechanism therefor including a cam wheel coaxial with said table and carrying a plurality of coaxial cam tracks.
52. In a phonograph, a rotating table rotatable on a stationary axis and having upstanding record centering means thereon, means for rotating said table throughout the operation of the phonograph, cooperating mechanisms operative while said table is rotating for reproducing a series of records thereon and discharging the same therefrom and controlling mechanism therefor including cam means rotatable while the table is rotating and having cooperating means operative by said cam means for controlling said mechanisms to effect operation thereof in timed relation to one another while said table continues to rotate.

53. In a phonograph, a rotating table rotatable on a stationary axis, cooperating record supplying, reproducing, and discharging mechanisms, and controlling mechanism therefor including a cam wheel coaxial with said table disposed beneath the latter and controlling each of said mechanisms.
54. In a phonograph, a rotating table rotatable on a stationary axis, a driving motor coaxial with the table, cooperating record supplying, reproducing, and discharging mechanisms, and controlling mechanism therefor including a cam wheel between said motor and table and controlling each of said mechanisms.
55. In a phonograph, a record rotating table, a record magazine offset laterally relative to said table, a movable reproducer mechanism, controlling cam means movable about the axis of said table, and operative connections controlled by said cam means for supplying to said table a record from said magazine and moving said reproducer mechanism into and out of reproducing relation with said record.
56. In a phonograph, mechanism for reproducing and discharging a series of records of the same diameter including a rotating table and a reproducer, mechanism including a cam member controlling said reproducing and discharging mechanism, a motor driving said table, driving connections between said motor and cam including a clutch controlled by said reproducer, means for holding said clutch disconnected during the actual playing of each record, and means adjustable to effect different movements of said reproducer into different initial record engaging positions on records of different diameters while continuing to control said clutch, and manually operable mechanism having a manually adjustable controlling member for adjusting said first mentioned mechanism to reproduce automatically a series of records of another diameter.
57. In a phonograph, mechanism for reproducing a series of records including a rotating table and a reproducer movable below said table when the latter is empty, mechanism including a cam member controlling said reproducing mechanism, a motor driving said table, driving connections between said motor and cam including a clutch, means for disconnecting said clutch during the actual playing of each record, and means for rendering said disconnecting means inoperative when said reproducer moves below said table and while said motor continues to drive said table.
58. In a phonograph, mechanism for reproducing a series of records including a rotating table, mechanism including a cam member controlling said reproducing mechanism, a motor driving said table, driving connections between said motor and cam including a clutch, means for disconnecting said clutch during the actual playing of each record, and means for stopping and starting said cam when said clutch is connected.
59. In a phonograph, mechanism for reproducing a series of records, mechanism including a rotating cam controlling said reproducing mechanism, and mechanism for starting and stopping said cam including a projection movable with said cam and a cooperating toothed member operative to stop and release said cam.
60. In a phonograph, mechanism for reproducing a series of records, mechanism including a rotating cam controlling said reproducing mechanism, mechanism for starting and stopping said cam including a projection movable with said
- cam and a cooperating toothed member operative to stop and release said cam, and means for adjusting said toothed member to vary the number of revolutions of the cam.
61. In a phonograph, mechanism for reproducing a series of records, mechanism including a rotating cam controlling said reproducing mechanism, mechanism for starting and stopping said cam including a projection movable with said cam and a cooperating toothed member operative to stop and release said cam, means for adjusting said toothed member to vary the number of revolutions of the cam, and means for holding said toothed member in different positions.
62. In a phonograph, mechanism for reproducing a series of records having record receiving means, mechanism including a rotating cam controlling said reproducing mechanism, mechanism for starting and stopping said cam including a projection movable with said cam and a cooperating toothed member operative to stop and release said cam, and means for adjusting said toothed member to vary the number of revolutions of the cam, said last means being actuated by the insertion of each record in said receiving means.
63. In a phonograph, mechanism for automatically reproducing records including a record receiving magazine adapted to have one or more records inserted therein, means automatically operative upon the insertion of the first record in said magazine to start the automatic reproduction of that record, and means to continue the automatic operation of said mechanism on successive records so long as an unplayed record remains in said phonograph.
64. In a phonograph, mechanism for automatically reproducing a series of records including a reproducer, a magazine, a table on which the records are reproduced, and co-operating record feeding and discharging mechanisms, and controlling mechanism for effecting automatic reproduction and discharge of said records successively including means for setting said feeding, reproducing and discharging mechanisms in operation upon the first record of the series upon the insertion of said record in said magazine.
65. In combination, a rotatable table having an upright axis, a cam coaxial with and below said table, a magazine supporting a record at one side of said axis, a record receptacle at one side of said axis, and means controlled by said cam for supplying a record from said magazine to said table, reproducing the same thereon, and discharging the same into said receptacle.
66. In combination, a rotatable table having an upright axis, a cam coaxial with and below said table, a magazine supporting a record at one side of said axis, a record receptacle at one side of said axis, and means disposed substantially within the vertical limits established by said magazine and cam and controlled by said cam for supplying a record from said magazine to said table, reproducing the same thereon, and discharging the same into said receptacle.
67. In a phonograph, a record magazine including a movable chain member and a cooperating record support, each disposed to support an edge of a substantially horizontal record, means for releasing the record from the chain member, a horizontal record rotating table, and means for delivering the released record into centered position thereon.
68. In a phonograph, a record magazine including a movable chain member and a coop-

- erating record support, each supporting an edge of a record, and means for releasing the record from the chain member including a rotating cam member.
- 5 69. In a phonograph, a record magazine comprising cooperating oppositely disposed record edge supporting and releasing means supporting a record in substantially horizontal position, means for adjusting one of the same relative to 10 the other to accommodate records of different size, and record feeding mechanism receiving a record from said first mentioned means and adjustable by said last mentioned means to accommodate records of different size.
- 15 70. A record magazine including a supporting member adapted to support the edge of a horizontal record on its top and having an inclined surface leading from its top and a reversely tapering portion intermediate its ends.
- 20 71. In a record magazine, a record edge supporting mechanism including an endless chain having laterally extending spaced portions adapted to support the edges of a series of records.
- 25 72. In a phonograph, a record edge supporting mechanism including an endless chain having laterally extending spaced portions adapted to support the edges of a series of records, and means for causing said chain to travel to release a record.
- 30 73. In a phonograph, record releasing mechanism including an endless chain having laterally extending spaced portions adapted to support the edges of a series of records, a toothed member rotatable with said chain by the weight of the records, and means for intermittently releasing said toothed member.
- 35 74. In combination, a record magazine comprising a stationary record edge supporting member having a relieved surface facilitating the withdrawal of the bottommost record of a series of records supported thereon, and cooperating oppositely located means supporting the opposite edges of said records in vertically spaced relationship and having provision for successively lowering the bottommost record.
- 40 75. In a phonograph, a record magazine comprising cooperating oppositely disposed record edge supporting and releasing means supporting a record in substantially horizontal position, one of said means being stationary and the other movable during the release of a record, and mechanism including an adjustable controlling member and means operable thereby for adjusting the stationary means laterally to accommodate records of different size.
- 45 76. In a phonograph, a record magazine comprising cooperating record supporting means adjustable relative to one another to accommodate records of different size, a record rotating table, and record feeding and guiding means adjacent the latter for delivering a record from said supporting means to said table and correspondingly adjustable in size by the adjustment of said supporting means relative to one another.
- 50 77. In a phonograph, a record magazine comprising cooperating record supporting means adjustable to accommodate records of different size, record feeding means receiving a record therefrom and correspondingly adjustable in position by the adjustment of said supporting means, a record rotating table receiving the fed records, and reproducer mechanism acting on records on said table and correspondingly adjustable in range by the adjustment of said supporting means.
- 55 78. In a phonograph, a magazine including record releasing means, a record rotating table, feeding means feeding a released record laterally onto said table, and means for simultaneously adjusting said magazine and feeding means to accommodate records of different size.
- 60 79. In a phonograph, a magazine including record releasing means, a record rotating table, feeding means feeding a released record laterally onto said table, and means for adjusting both said magazine and feeding means to accommodate records of different size having a single manually adjustable member.
- 65 80. In a phonograph, a record rotating table, and feeding means adapted to feed a record laterally over said table including rotary means engaging the under side of a horizontal record and also having driving means therefor engaging and driven by the table.
- 70 81. In a phonograph, a record rotating table having a centering pin, means for feeding a record horizontally over said pin while supported thereon and into centered position on the pin, and means for adjusting said feeding means to feed records of different diameter through different distances into centered position.
- 75 82. In a phonograph, a magazine adapted to carry superimposed horizontal records, a laterally offset record rotating table having a centering pin, a plurality of co-operating means delivering one to the other and successively acting on the record disposed throughout their operation at one side of said table and co-operating in supplying a record laterally from said magazine over said pin and into centered position thereon.
- 80 83. In a phonograph, a magazine adapted to carry superimposed records therein, a laterally offset record rotating table having a centering pin, and mechanism for successively placing records in said magazine on said table having a plurality of co-operating record engaging means delivering to one another and successively separating and feeding each record laterally over said pin and into centered position thereon while supported by said pin.
- 85 84. In a phonograph, a record rotating table having a projecting centering pin, and mechanism comprising a plurality of co-operating relatively movable means successively acting on a laterally offset record and disposing the under surface of said record on said pin and feeding said record laterally into centered position while traveling on said pin.
- 90 85. In a phonograph, a record rotating table having an upstanding centering pin, a magazine supporting records one above another with their axes laterally offset relative to said pin, and record feeding mechanism comprising record separating means for separating the bottommost record and co-operating relatively movable means for feeding the bottommost record laterally relative to said magazine and while in contact with the upper end of said pin into centered position on the latter.
- 95 86. In a phonograph, a record rotating table rotatable on an upright stationary axis, a laterally spaced magazine having means operative to discharge a record, and means set in operation by a record discharged from said magazine for feeding the record onto the table.
- 100 87. In a phonograph, a record rotating table, a laterally spaced magazine, means for discharging a record therefrom, and means set in operation by a record discharged from said magazine for feeding the record onto the table including

pivottally mounted wheel members respectively engageable with the record and said table.

88. In a phonograph, a record rotating table, a laterally disposed magazine, means for discharging a record therefrom, a support engageable by one side of a discharged record, and means engageable by the other side of said record and set in operation thereby for feeding the record onto the table.

10 89. In a phonograph, a record rotating table, a laterally spaced magazine, mechanism for successively reproducing records on said table, mechanism for discharging the reproduced record in a direction away from the record path between 5 said magazine and table, and mechanism other than said discharging mechanism for supplying a new record from the bottom of said magazine on to said table having means movable relative to said discharging mechanism disposed, ready 15 for operation in record feeding position beneath said magazine during reproduction, and means for actuating said last-mentioned means to feed a new record laterally relative to said magazine and on to the table upon movement of the reproduced record away from said path.

90. In a phonograph, a record rotating table having a centering pin, and means for feeding a record laterally over said pin and into centered position on the pin including rotatable record 20 feeding means engaging the record.

91. In a phonograph, a record rotating table having a centering pin, and means for feeding a record laterally over said pin and into centered position on the pin including rotatable record 25 feeding means engaging the record and the table and moved into operative engagement with the latter by the weight of a record.

92. In a phonograph, a record rotating table having a centering pin, and means for feeding a record laterally over said pin and into centered 30 position on the pin including rotatable record feeding means engaging the record and moved into and out of driving engagement with the table by movement of the record.

45 93. In a phonograph, a record rotating table rotatable on a vertical axis, and record centering means adapted to place a record in centered position on the table and including a plurality of members engageable with the record at a plurality of peripherally spaced points during the centering operation, and means for adjusting 50 said members to adapt them to center records of different diameter.

94. In a phonograph, mechanism for automatically reproducing a series of records including a 55 reproducer, a table on which the records are reproduced, and feeding mechanism having a magazine, and controlling mechanism for effecting automatic reproduction of said records successively 60 and having means for automatically setting said feeding and reproducing mechanisms in operation to feed the record to said table and reproduce the same upon the deposit of the first record of the series in said magazine.

65 95. In a phonograph, a record rotating table rotatable on a vertical axis, a laterally offset magazine having record discharging means, and mechanism operative to center the discharged record on said table including means controlled 70 by the record to be centered.

96. In a phonograph, a record rotating table rotatable on a vertical axis, a laterally offset magazine having record discharging means, and mechanism operative to center the discharged 75 record on said table including means controlled

by the record to be centered and differently adjustable relative to the table axis to accommodate records of different diameter.

97. In a phonograph, a record magazine adapted to support a plurality of records one above the other, a laterally offset record rotating table, and mechanism for delivering the bottommost record from the magazine laterally above the table and centering the same on said table including record centering means controlled by the 10 record to be centered.

98. In a phonograph, a record rotating table, a record magazine laterally offset with respect thereto and adapted to support a series of records in superimposed position, means for permitting 15 the bottommost record to move by gravity relative to the magazine, and record centering mechanism automatically operative upon said record and including means controlled by the record.

99. In a phonograph, a record rotating table, a 20 record magazine laterally offset with respect thereto and adapted to support a series of records in superimposed position, means for permitting the bottommost record to move by gravity relative to the magazine, and record centering mechanism automatically operative upon said record and including means controlled by the record 25 and means adjustable toward and from the table axis to accommodate records of different size.

100. In a phonograph, a record magazine 30 adapted to support records in substantially horizontal position and discharge the same one by one and having means whereby said magazine may be filled from the top or the side at will.

101. In combination, mechanism adapted to 35 play a series of records including a record magazine having means for enabling the same to be filled with records from the end or side thereof at will while said magazine remains assembled and supporting records and releasing them one 40 by one, and controlling means for setting said mechanism to effect automatic reproduction of all of said records irrespective of the method of insertion.

102. In a phonograph, a record rotating table 45 having an upstanding centering pin, a laterally spaced magazine having record releasing means, and feeding means beneath said magazine for feeding a record released from said magazine laterally relative to said feeding means in a path 50 above said pin and effecting lowering of said record into centered position thereon.

103. In a phonograph having record rotating 55 means, a record magazine spaced laterally therefrom, and a record receptacle for reproduced records spaced laterally from said rotating means, means for disposing a record in released position beneath said magazine, cooperating means for feeding said record laterally from said released 60 position beneath said magazine into centered position on said rotating means, means for reproducing the record on said rotating means, and means for discharging the reproduced record into said receptacle.

104. In a phonograph, record supporting and 65 feeding mechanism comprising a record support for carrying a series of records thereon one above the other and having spaced supporting means for the bottommost record and one of said means supporting the periphery of that record and adjustable laterally to accommodate records of different diameter while the other supporting means occupies the same position when supporting records of different diameter, a record rotating table rotatable on a vertical axis, means for 70

75

- successively releasing the bottommost records one by one in different lateral positions of said peripheral supporting means and successively disposing the next record in bottommost position 5 on both of said supporting means, means for centering on said table released records of different diameter, and means for adjusting said record supporting and feeding mechanism to accommodate records of different diameter having 10 a single control member and operative connections thereto for effecting adjustment upon operation of said member.
105. In a phonograph, a record rotating table, means extraneous of the record apertures and 15 selectively operative on records of different diameter for delivering to said table through paths of different length, and while said table is rotating, records of different diameter, automatic reproducer mechanism adapted to reproduce records on said table, and means for automatically adapting said reproducer mechanism to reproduce records of different diameter upon delivery of the latter upon said table.
106. In a phonograph, record rotating means, 20 means for delivering records of different size thereto including spaced laterally movable members adjustable to accommodate records of different size and means for propelling a record between said laterally movable members in its 25 path to the table, automatic reproducer mechanism, and means operative upon the adjustment of said laterally movable members for automatically adapting the reproducer mechanism to reproduce records of different size.
107. In a phonograph, a record rotating table, a magazine carrying a series of records and adapted to receive records of different size, means extraneous of the record apertures for delivering a record in said magazine onto the table irrespective of the size of the record and including an adjustable member and means for propelling records of different diameter relative to said member and through paths of different length to said 30 table, automatic reproducer mechanism, and means adjustable upon adjustment of said member for automatically adjusting the range of swing of said reproducer to adapt it to reproduce records of different size.
108. In a phonograph, a record rotating table 35 rotatable on a vertical axis and having centering means, a laterally offset record magazine adapted to present records of different diameter in delivery position with their axes at different distances laterally from said centering means, and selectively operative mechanism for feeding records of different diameter from said delivery position toward said table and through different distances into centered position thereon.
109. In a phonograph, a record magazine 40 adapted to be filled from the top and to support records of different diameter in delivery position therein with their central apertures at different distances from one side of the magazine, a record rotating table rotatable on a vertical axis and disposed laterally with respect to said magazine and having record centering means, and means for delivering records from said delivery position in said magazine into centered position on said table irrespective of the variation in the distance between the axis of the record in the magazine and said centering means.
110. In a phonograph, a record magazine 45 adapted to support records of different diameter in delivery position therein with their central apertures at different distances from a common point in said magazine, a record rotating table rotatable on a vertical axis and disposed laterally with respect to said magazine and having record centering means at different distances from the central apertures of records of different diameter, means wholly extraneous of the record apertures for delivering records from said delivery position in said magazine into centered position on said table irrespective of the variation in the distance between the axis of the record in the magazine and said centering means, reproducer mechanism automatically operative on a record upon its delivery to said table, and means for automatically adjusting the initial record engaging position of said reproducer mechanism to accord with the diameter of the record to be reproduced.
111. In a phonograph, a record rotating table having upstanding centering means, means for rotating said table throughout the operation of the phonograph, a laterally spaced record supply, 50 means for delivering records of different diameter from said supply in the same direction through lateral paths of different length into centered position on said table while the latter is rotating, and reproducer mechanism automatically adjustable to reproduce centered records of different diameter upon delivery in centered position.
112. In a phonograph, record rotating mechanism rotatable on a vertical axis and having record centering means, means adjustable to deliver either successive records of the same diameter or records of different diameter in the same direction over said centering means and into centered position thereon while said mechanism is rotating, reproducer mechanism automatically operative to reproduce a record following centering of the same, and means operative upon adjustment of said delivery means to effect centering of a record of different diameter, also 55 automatically adjusting the movement of said reproducer mechanism to enable it to reproduce a record of the new diameter.
113. In a phonograph, record rotating mechanism, means adapted to deliver laterally records of different diameter in the same direction through paths of different lengths over said centering means and into centered position thereon while said mechanism is rotating, reproducer mechanism automatically operative to reproduce a record following centering of the same, and means operative automatically prior to beginning reproduction of the centered records automatically adjusting the initial record engaging position of the reproducer mechanism to enable 60 the latter to reproduce records of different diameter.
114. In a phonograph, a magazine, a laterally offset rotating table, a reproducer, and mechanism for delivering records of different diameter from said magazine laterally through paths of different lengths into centered position on said table and effecting reproduction of the centered records, including means engaged and set in operation by records of different diameter in their 65 passage between said magazine and table.
115. In a phonograph, a record rotating table rotatable on a vertical axis, and mechanism for automatically reproducing records thereon including mechanism adjustable to center thereon records of different diameter, reproducer mechanism adjustable to reproduce centered records of different diameter, and means whereby adjustment of one adjustable mechanism correspondingly adjusts the other.

116. In a phonograph, a record rotating table, means for rotating said table throughout the operation of the phonograph, and mechanism for automatically reproducing standard records on said table including mechanism differently adjustable to feed through lateral paths of different length and center on said table while said table is rotating standard records of different diameter, and reproducer mechanism automatically adjustable to reproduce standard centered records of different diameter upon delivery on said table.
117. In a phonograph, a record rotating table having centering means, means for rotating said table throughout the operation of the phonograph, and mechanism for automatically reproducing standard records on said table including mechanism operative to feed standard records of different diameter bodily laterally over said table and laterally through different distances over said centering means into centered position thereon while said table is rotating, automatic, reproducer mechanism adjustable to reproduce standard centered records of different diameter, and means whereby prior to reproduction of a centered record of different diameter the reproducer mechanism is correspondingly adjusted automatically.
118. In a phonograph, a record magazine having records therein one above another, a laterally offset record rotating table, mechanism for delivering the bottommost record from said magazine into centered position thereon including adjustable centering means adapted to center records of different diameter, and reproducer mechanism automatically adjusted to reproduce a record of the new diameter.
119. In a phonograph, a magazine adapted to hold records one above another and records of different diameter, a laterally offset record rotating table, and record feeding mechanism automatically operative upon records in said magazine and having centering means movable into different positions laterally relative to the table axis to center records of different diameter on said table.
120. In a phonograph, a magazine adapted to hold records one above another and records of different diameter, a laterally offset record rotating table, record feeding mechanism automatically operative upon the bottommost record and having centering means movable into different positions laterally relative to the table axis to center records of different diameter on said table, reproducer mechanism, and means whereby said mechanism is automatically adjusted to correspond with the diameter of the record centered.
121. In a phonograph, a magazine adapted to receive records of different diameter, a laterally offset record rotating table, and mechanism for centering on the latter records from said magazine despite variations in diameter including means for effecting record movement bodily laterally above the table and engaging and bringing said record into centered position, and means whereby said means may be adjusted to vary the length of lateral movement of the record axis to cooperate with records of different diameter.
122. In a phonograph, a magazine, a laterally offset record rotating table rotatable on a vertical axis, record delivery mechanism differently adjustable to deliver records of different diameter and having adjustable means engageable with the edge of a record delivered laterally between said magazine and table, and reproducer mecha-
- nism automatically adjusted to cooperate with a record of different diameter upon adjustment of said means.
123. In a phonograph, a record rotating table rotatable on a vertical axis, a record magazine wherein records are disposable one adjacent another with records of different diameters having their axes at different distances from the table axis when in delivery position in said magazine, mechanism for automatically supplying from said delivery position to said table either large or small records in said magazine having adjustable record supplying means for supplying records of different diameter to said table while the latter rotates, and automatic reproducing means operating with records on said table, and automatically adjusted into different starting positions upon adjustment of said record supplying means.
124. In a phonograph, a record rotating table rotatable on a vertical axis, a record magazine wherein records are disposable one above another with records of different diameter having their axes at different distances from the table axis, and mechanism comprising adjustable record supplying means acting on the bottommost record in said magazine and reproducer mechanism automatically adjusted thereby whereby irrespective of predetermined variations in diameter of the records in said magazine, the bottommost records therein may be automatically supplied through the required distances into centered position on said table and reproduced on said table.
125. In a phonograph, a record rotating table comprising a record supporting disc rotatable on a fixed vertical axis, a record magazine wherein records are disposable one above another when ready for delivery to said table, mechanism whereby either large or small records in said magazine may be automatically delivered to said table through lateral paths of different length and reproduced on said table, and discharging mechanism independent of said last mentioned mechanism but operative in timed relation thereto for discharging the reproduced records from said table.
126. In a phonograph, a record table rotatable on a vertical axis, a laterally offset magazine wherein records are disposable one above another, mechanism acting on the bottommost record in said magazine and delivering the same laterally in centered position on the table, and adjustable control means for adjusting said mechanism to center records of different diameter on the table.
127. In a phonograph, a record table rotatable on a vertical axis, a laterally offset magazine adapted to carry records one above another when ready for delivery to said table and records of different diameter with their axes differently spaced laterally from the axis of said table, and means operative irrespective of the different distances between the record axes and the table axis for supplying records of different diameter from said magazine laterally across the table axis through different distances into centered position on said table and reproducing the same.
128. In a phonograph, a record table rotatable on a vertical axis, a magazine adapted to carry records one above another and records of different diameter with their axes differently spaced laterally from the axis of said table, means operative irrespective of the different distance between the record axes and the table axis for supplying

- the bottommost records of either diameter from said magazine to said table, and reproducer mechanism automatically adjustable to co-operate with records of different diameter upon their supply to the table.
129. In a phonograph, a magazine wherein records are disposable prior to reproduction, a record rotating table rotatable on a vertical axis, reproducer mechanism including a swinging reproducer movable to co-operate with a record on said table and movable below the table when no record is thereon, mechanism for successively supplying records from said magazine to and discharging the same from said table, and controlling means for effecting automatic operation of said mechanism from predetermined starting positions to supply, reproduce and discharge a record and effecting the return of said mechanism to said starting positions when said reproducer moves below said table.
130. In a phonograph, a magazine wherein records are disposable prior to reproduction, a record rotating table rotatable on a vertical axis, reproducer mechanism including a swinging reproducer movable to co-operate with a record on said table and movable below the table when no record is thereon, record feeding and discharging mechanism for supplying records from said magazine to and discharging the same from said table, and controlling means for effecting automatic operation of said mechanisms from predetermined starting positions to supply, reproduce and discharge records and having a controlling member actuated by said reproducer when it moves below said table and means for thereafter returning said mechanisms to starting position and stopping the same therein.
131. In a phonograph, a record table rotatable on a vertical axis, a magazine adapted to carry records of different diameter and wherein records of different diameter are disposable with their axes at different distances from the table axis, mechanism operative while said table is rotating for supplying to said table automatically from said magazine records of either diameter in said magazine, and reproducer mechanism for automatically reproducing records on said table automatically adjustable while the table is rotating to co-operate with a record of a different diameter when the latter is supplied to said table.
132. In a phonograph, a magazine adapted to carry superimposed records therein, a laterally offset record rotating table having centering means, and mechanism for successively placing the bottommost records in said magazine on said table having record separating means and spaced record engaging members receiving the separated record therefrom and disposed on opposite sides of the axes of the record and said table and at the side of the table toward said magazine and feeding said record into centered position.
133. In a phonograph, a record magazine adapted to carry superimposed records therein, a laterally offset record rotating table having centering means, and mechanism for successively placing the bottommost records in said magazine in centered position on said table comprising endless record separating means separating the bottommost record and co-operating record engaging means feeding the separated record laterally into centered position.
134. In a phonograph, a record magazine supporting a plurality of superimposed records, a laterally offset record rotating table having cen-
- tering means, means for successively feeding the bottommost records into centered position, reproducer mechanism automatically operative successively on the centered records, means for automatically discharging reproduced records from said table, and adjustable controlling means for adapting certain of said elements to operate automatically to effect automatic feeding, reproduction and discharge of large or small records.
135. In a phonograph, a record magazine adapted to carry superimposed records therein and to receive records of different diameter, a laterally offset record rotating table having record centering means spaced by different distances from the axes of records of different diameter in said magazine, and mechanism for supplying the records from said magazine into centered position on said table having means for feeding records of different diameter laterally through paths of different length.
136. In a phonograph, a magazine adapted to carry therein superimposed records and to receive records of different diameter, a laterally offset record rotating table having centering means spaced by different distances from the axes of records of different diameter in said magazine, and mechanism for supplying records of different diameter laterally from said magazine on to said centering means, and means for adjusting the length of feed thereof to accommodate records of different diameter.
137. In a phonograph, a magazine adapted to carry therein superimposed records and to receive records of different diameter, a laterally offset record rotating table having centering means spaced by different distances from the axes of the records of different diameter in said magazine, and mechanism for supplying records of different diameter laterally from said magazine on to said centering means irrespective of said differences in distance having feeding means initiating feeding of records of different diameter at different laterally spaced points.
138. In a phonograph, a magazine adapted to carry therein superimposed records and to receive records of different diameter, a laterally offset record rotating table having centering means spaced by different distances from the axes of the records of different diameter in said magazine, and mechanism for supplying records of different diameter from said magazine on to said centering means having feeding means adjustable to feed records of different diameter laterally through paths of different length and centering all of the records while the same are supported on said centering means.
139. In a phonograph, a record magazine adapted to carry therein superimposed records and to receive records of different diameters, a laterally offset record rotating table having centering means spaced by different distances from the axes of records of different diameter in said magazine, means for supplying records of different diameter laterally from said magazine through paths of different length into centered position on said table, and cooperating automatically adjusted reproducer mechanism engaging the centered records of different diameter at different distances from said centering means.
140. In a phonograph, a record magazine adapted to carry superimposed records and to receive records of different diameter, a laterally offset record rotating table having record centering means, feeding mechanism adjustable to center

thereon records of different diameter, reproducer mechanism adjustable to reproduce centered records of different diameter, and controlling mechanism controlling the operation of said feeding and reproducer mechanisms having controlling means engageable by a record and occupying different positions for records of different diameter.

141. In a phonograph, a record magazine 10 adapted to carry superimposed records and to receive records of different diameter, a laterally offset record rotating table having centering means, record feeding mechanism adjustable to center records of different diameter on said table, reproducer mechanism adjustable to reproduce centered records of different diameter, and controlling mechanism for said mechanisms having adjusting means for said feeding mechanism, adjusting means for said reproducer mechanism, 20 and controlling means for both of said adjusting means occupying different positions for records of different diameter.

142. In a phonograph, a record rotating table rotatable on a vertical axis and having an axial 25 centering pin, mechanism for automatically reproducing successively centered records on said table, and mechanism for successively centering records on said table having a plurality of record feeding means one delivering to another and each 30 engaging each record wholly at one side of the table axis and disposed on that side of said axis during reproduction.

143. In a phonograph, a record rotating table, a magazine carrying a series of superimposed 35 records and adapted to carry records of different predetermined diameters, means for delivering the bottommost record in said magazine onto the table adjustable to deliver records of said different diameters, reproducer mechanism, 40 means automatically adjustable with said adjustable delivery means for adjusting the range of swing of said reproducer mechanism to adapt it to reproduce records of the different diameters delivered on said table and means operative in 45 timed relation to said reproducer mechanism for discharging the reproduced record from said table irrespective of the diameter of the record.

144. In a phonograph, a record rotating table rotatable on a vertical axis and having centering 50 means, a laterally offset record magazine adapted to support in superimposed relation records of either of a plurality of predetermined diameters with the axes of records of different diameter at different distances laterally from the table axis, 55 and adjustable means for feeding records of either diameter from the bottom of said magazine and placing said records in centered position on said table.

145. In a phonograph, a rotating table rotatable 60 on a vertical axis, and mechanism for delivering a record in centered position on the table while the latter is rotating on said axis including record receiving means adapted to receive a new record while a record therein is being delivered therefrom, record delivery means, and controlling 65 means for the latter engaged while said delivery means is inoperative by the record to be centered and actuated thereby to set said delivery means in operation.

146. In a phonograph, a single record rotating 70 table rotatable on a vertical axis and having a centering pin projecting upward from said table, mechanism for delivering a record over said pin and into centered position on said pin and table 75 while said table is rotating in horizontal position,

reproducer mechanism, and mechanism for actuating said reproducer mechanism to reproduce the centered record having controlling means engaged and actuated by the record to be reproduced.

147. In a phonograph, a single record rotating 10 table rotatable on a vertical axis and having centering means, mechanism for delivering a record in centered position thereon while said table is rotating in horizontal position having a control- 15 ling member engaged and actuated by the record to be delivered, reproducer mechanism for reproducing the record when centered, and means for adjusting said delivery mechanism and member and said reproducer mechanism to accommo- 15 date records of different diameter.

148. In a phonograph, a record rotating table rotatable on a vertical axis, a record magazine supporting the records to be reproduced one above another with their axes laterally offset relative 20 to the table axis, means for separating the bottommost record from said magazine, and co-operating means disposed on the same side of the table axis as said magazine and movable relative 25 to said means receiving the record therefrom and delivering it bodily laterally into centered position on said table.

149. In a phonograph, a record rotating table rotatable on a vertical axis, a record magazine supporting the records to be reproduced one above 30 another with their axes laterally offset relative to the table axis, means for separating the bottommost record from said magazine, and co-operating means movable relative to said means receiving the record therefrom and delivering it 35 into centered position on said table, both of said means being disposed and engaging the record on the same side of the table axis as said magazine.

150. In a phonograph, a record rotating table 40 rotatable on a vertical axis, a record magazine supporting the records to be reproduced one above another with their axes laterally offset relative to the table axis, means for separating the bottommost record from said magazine, and co-operating 45 means receiving the record from said first mentioned means and delivering it into centered position on said table, said first mentioned means comprising an endless conveyor having abutment means engageable with the periphery of a record 50 to separate the same and said co-operating means engaging the record after it has been separated from the other records.

151. In a phonograph, a record rotating table 55 rotatable on a vertical axis, a record magazine supporting the records to be reproduced one above another with their axes laterally offset relative to the table axis, means for separating the bottommost record from said magazine, and co-operating means receiving the separated record from 60 said first mentioned means and delivering it into centered position on said table, said first mentioned means including an endless conveyor at one side of said table and said last mentioned means being pivoted on the same side of the table. 65

152. In a phonograph, a record rotating table 70 rotatable on a vertical axis, a record magazine supporting the records to be reproduced one above another with their axes laterally offset relative to the table axis, means for separating the bottommost record from said magazine, co-operating 75 means disposed and operating between the axes of the records in said magazine and the table axis receiving the record from said first mentioned means and delivering it into centered position on 75

- said table, means for successively reproducing the records on said table, and mechanism for successively removing the reproduced records from said table.
- 5 153. In a phonograph, a record rotating table rotatable on a vertical axis, a record magazine supporting the records to be reproduced one above another with their axes laterally offset relative to the table axis, means for separating the bottommost record from said magazine, co-operating means receiving the record from said first mentioned means and delivering it into centered position on said table, means for successively reproducing the records on said table, and mechanism for successively removing the reproduced records from said table comprising means disposed beneath the centered records during reproduction and means for effecting relative movement between said last mentioned means and said records to discharge the latter.
- 10 154. In a phonograph, a record support for supporting a series of records in superimposed relation having spaced supporting means for the bottommost record and one of said means engaging the periphery of said record and adjustable laterally to support records of different diameters, a record rotating table rotatable on a vertical axis, and mechanism adjustable to cooperate with said peripheral supporting means in different positions of adjustment thereof for successively supplying to said table the bottommost record on said spaced supporting means while successively disposing the next record in bottommost position on said spaced supporting means.
- 15 155. In a phonograph, record supporting means for carrying a series of records thereon one above the other and having spaced record supporting means for the bottommost record and one of said means supporting the periphery thereof and adjustable to support records of different diameter, a record rotating table rotatable on a vertical axis, mechanism for supplying the bottommost records to said table likewise adjustable to supply records of different diameter having means for successively releasing the bottommost records one by one from both said supporting means while successively disposing the next record in bottommost position on both of said supporting means, and adjusting mechanism having a controlling member and operative connections thereto for adjusting said peripheral supporting means and said adjustable supply means upon operation of said member.
- 20 156. In a phonograph, a record support supporting a series of records in superimposed relation having spaced supporting means for the bottommost record and one of said means engaging the periphery of said record, a record rotating table rotatable on a vertical axis, mechanism for successively feeding the bottommost record on said supporting means onto said table while successively disposing the next record in bottommost position on said supporting means, means for adjusting said peripheral supporting means to accommodate records of different diameter, and means for adjusting said feeding means to accommodate records of different diameter.
- 25 157. In a phonograph, a record support for carrying a series of records thereon one above the other and having spaced supporting means for the bottommost record and one of said means supporting the periphery of that record and adjustable laterally to accommodate records of different diameter while the other supporting means occupies the same position when supporting
- records of different diameter, a record rotating table rotatable on a vertical axis, means for successively releasing the bottommost records one by one in different lateral positions of said peripheral supporting means and successively disposing the next record in bottommost position on both of said supporting means, and means for centering on said table released records of different diameter.
- 30 158. In a phonograph, a record rotating table rotatable on a vertical axis, a record magazine supporting a series of records one above the other with their axes in laterally offset relation to the table axis, and mechanism for successively delivering the bottommost record in said magazine laterally into centered position on said table having record separating means operable on said bottommost record in the magazine, and also co-operating record centering means disposed at the side of the table axis toward said magazine and movable relative to said first mentioned means and the record while supporting the latter also releasing said record when the latter is in centering position above the table.
- 35 159. In a phonograph, a record rotating table rotatable on a vertical axis, a record magazine supporting a series of records one above the other with their axes laterally offset relative to the table axis, means for successively delivering records in said magazine laterally into centered position on said table engaging the records at the side of said table toward said magazine and feeding the records laterally in advance thereof into centering position on the table and means controlling the operation of said delivering means and controlled by the records fed.
- 40 160. In a phonograph, a record rotating table rotatable on a vertical axis, a record magazine supporting a series of records one above the other with their axes offset relative to the table axis, means for successively delivering the bottommost record in said magazine laterally into centered position on said table engaging the records at the side of said table toward said magazine and feeding the records laterally in advance thereof into centering position on the table and means controlling the operation of said delivering means and controlled by the records fed.
- 45 161. In a phonograph, a record rotating table rotatable on a vertical axis, a record magazine supporting a series of records one above the other with their axes laterally offset relative to the table axis, means for successively delivering records in said magazine laterally into centered position on said table engaging the records at the side of said table toward said magazine and feeding the records laterally in advance of said delivering means into centering position on the table, means for successively reproducing said records on said table, and mechanism including means movable under said records upon reproduction for successively effecting removal of the reproduced records from said table.
- 50 162. In a phonograph, a record rotating table rotatable on a vertical axis, a record magazine supporting a series of records one above the other with their axes laterally offset relative to the table axis, means for successively delivering records in said magazine laterally into centered position on said table engaging the records at the side of said table toward said magazine and feeding the records laterally in advance of said delivering means into centering position on the table, means for successively reproducing said records on said table, mechanism including means

movable under said records upon reproduction for successively effecting whirling off of the reproduced records by said table, a receptacle disposed in alignment with said magazine and table, and 5 guiding means for directing the whirling discharged records into said receptacle.

163. In a phonograph, a record rotating table rotatable on a vertical axis, means for reproducing records as they are successively delivered on said table, a record magazine supporting during reproduction the records to be thereafter reproduced, one above the other with their axes laterally offset relative to the table axis, and mechanism for successively disposing on said table the bottommost record in said magazine comprising a plurality of co-operating means each moving the record relative to the other and disposed during reproduction on the same side of said table axis.

164. In a phonograph, a record rotating table rotatable on a vertical axis, means for reproducing records as they are successively delivered on said table, a record magazine supporting during reproduction the records to be thereafter reproduced, one above the other with their axes laterally offset relative to the table axis, and mechanism for successively disposing on said table the bottommost record in said magazine comprising a plurality of co-operating means, one initially operable to dispose the record for engagement by the other and both disposed during reproduction on the same side of said table axis.

165. In a phonograph, a record rotating table rotatable on a vertical axis, means for reproducing records as they are successively delivered on said table, a record magazine supporting during reproduction the records to be thereafter reproduced, one above the other with their axes laterally offset relative to the table axis, and mechanism for successively disposing on said table the bottommost record in said magazine comprising a pair of cooperating record engaging and actuating means and having one of the same delivering to the other and the latter delivering the record in centered position and each co-operating to project the record laterally relative to and beyond each of said means and the other records in centered position on said table.

166. In a phonograph, a record rotating table rotatable on a vertical axis, means for reproducing records as they are successively delivered on said table, a record magazine supporting during reproduction the records to be thereafter reproduced, one above the other with their axes laterally offset relative to the table axis, and mechanism for successively disposing on said table the bottommost record in said magazine comprising a pair of co-operating record engaging and actuating means and having one of said means at one side of said table engaging the periphery of the bottommost record and acting to separate it from the others and deliver it to the other of said means and the latter means moving said record bodily laterally relative to the other records and beyond said latter means into centered position over said table.

167. In a phonograph, a record rotating table rotatable on a vertical axis, means for reproducing records as they are successively delivered on said table, a record magazine supporting during reproduction the records to be thereafter reproduced, one above the other with their axes laterally offset relative to the table axis, and mechanism for successively disposing on said table the

bottommost record in said magazine comprising a plurality of co-operating means and having one of the same delivering to the other and both co-operating to project the record laterally relative to each of said means and the other records, both of said means being disposed during reproduction on the same side of the table axis.

168. In a phonograph, a record rotating table rotatable on a vertical axis, means for reproducing records as they are successively delivered on said table, a record magazine supporting during reproduction the records to be thereafter reproduced, one above the other with their axes laterally offset relative to the table axis, and mechanism for successively disposing on said table the bottommost record in said magazine comprising a plurality of co-operating means both disposed during reproduction on the same side of said table axis and having one of said means engageable with the periphery of the bottommost record and both co-operating to discharge the record laterally relative to the other records.

169. In a phonograph, record carrying means supporting a series of records in horizontal relation one above the other, and mechanism for successively separating one of the end records from the others and delivering the same laterally relative to the remaining records comprising record separating means tilting the record to be separated relative to the others and co-operating means acting upon the thus separated record and delivering the same laterally relative to the other records.

170. In a phonograph, a record rotating table disposed in fixed planes throughout its operation, reproducer mechanism for automatically successively reproducing records thereon and having a part movable when the table is empty to intersect the planes normally occupied by a record being reproduced on said table, and mechanism for successively presenting new records for reproduction on said table set in operation by said reproducer mechanism when said part moves below said planes.

171. In a phonograph, a record rotating table disposed on a fixed vertical axis, reproducer mechanism for automatically successively reproducing records thereon having a reproducer co-operating with a record on said table and movable below the planes normally occupied thereby when no record is thereon, mechanism for discharging successive records from said table as the same are reproduced, mechanism for thereafter delivering successive new records for reproduction on said table while the latter continues to rotate, and means controlling said delivery mechanism actuated when said reproducer moves below said planes to advance the normal time of operation of said delivery mechanism when no record is on the table.

172. In a phonograph, a record rotating table rotatable on a vertical axis, and mechanism for successively disposing for reproduction on said table the bottommost record in a series of records disposed prior to reproduction one above the other with their axes laterally offset relative to the table axis, comprising a plurality of co-operating means each moving a record relative to the other and each disposed during reproduction on the same side of the table axis and one of the same delivering the record beyond it into centered position on said table.

173. In a phonograph, a record rotating table rotatable on a vertical axis, and mechanism for

successively disposing on said table for reproduction the bottommost record in a series of records disposed prior to reproduction one above the other with their axes laterally offset relative to the table axis, comprising a plurality of co-operating record engaging means disposed during reproduction on the same side of the table axis and one initially operable to dispose the record for engagement by the other and the latter means engaging and locating the record in centered relation to said table.

174. In a phonograph, a record rotating table rotatable on a vertical axis, and mechanism for successively disposing for reproduction on said table the bottommost record of a series of records disposed prior to reproduction one above the other with their axes laterally offset relative to the table axis, comprising a plurality of co-operating record engaging means and having one of said means delivering to the other and the latter means engaging and effecting the lateral disposition of the record relative to said first mentioned means and the other records in advance of said latter means.

175. In a phonograph, a record rotating table rotatable on a vertical axis, and mechanism for successively disposing for reproduction on said table the bottommost record in a series of records disposed prior to reproduction one above the other with their axes laterally offset relative to the table axis, comprising a plurality of co-operating record engaging means and having one of the same supporting the bottommost record prior to reproduction with its axis at one side of the table axis and delivering said record to the other means and the latter means constantly disposed at one side of the table axis and acting upon the record delivered thereto by said first mentioned means to effect movement of said record laterally relative to said first mentioned means and the other records.

176. In a phonograph, a record rotating table rotatable on a vertical axis, and mechanism for successively disposing for reproduction on said table the bottommost record in a series of records disposed prior to reproduction one above the other with their axes laterally offset relative to the table axis, comprising a plurality of co-operating means co-operating to dispose the bottommost record in centered position on said table and having means for moving the record into engagement with the other means and means acting upon engagement with the record to effect a lateral projection of the record relative to the other records and in advance of said last mentioned means in centered position over the table.

177. In a phonograph, a record rotating table rotatable on a vertical axis, mechanism for successively disposing for reproduction on said table the bottommost record in a series of records disposed prior to reproduction one above the other with their axes offset laterally relative to the table axis, comprising a plurality of co-operating means each disposed during reproduction on the same side of the table axis and each co-operating in projecting the bottommost record laterally relative to the other records in centered position over said table, means for reproducing records as they are successively delivered on said table, and vertically movable means inoperative during reproduction and automatically movable under a reproduced record on said table to effect removal of the latter from the table prior to the delivery on said table of a new record by said first mentioned mechanism.

178. In a phonograph, a record rotating table rotatable on a vertical axis, and mechanism for successively disposing for reproduction on said table the bottommost record in a series of records to be thereafter reproduced and disposed prior to reproduction one above the other with their axes laterally offset relative to the table axis, comprising a plurality of co-operating means having one of the same delivering said record to the other means and the latter means acting upon said record at one edge of the table to effect lateral movement of said record relative to the other records.

179. In a phonograph, a record rotating table rotatable on a vertical axis and having an axial centering pin, and mechanism for successively disposing for reproduction on said table the bottommost record in a series of records to be thereafter reproduced and disposed prior to reproduction one above the other with their axes laterally offset relative to the table axis, comprising a plurality of co-operating means having one of the same delivering said record to the other means and the latter means engaging the record only at one edge of the table and effecting lateral movement of said record relative to the other records and said pin into centered position above the latter.

180. In a phonograph, a record rotating table rotatable on a vertical axis and having an axial centering pin and an unobstructed space above the latter, and mechanism for successively disposing for reproduction on said table the bottommost record in a series of records to be thereafter reproduced and disposed prior to reproduction one above the other with their axes laterally offset relative to the table axis, comprising a plurality of co-operating means having one of the same delivering said record to the other means and the latter means constantly disposed at one edge of said table and engaging and effecting bodily lateral movement of the delivered record relative to the other records in said space above said pin.

181. In a phonograph, a record rotating table rotatable on a vertical axis, a magazine carrying a series of superimposed records with their axes laterally offset relative to the table axis during reproduction of a record on the latter, and mechanism for successively disposing for reproduction on said table the bottommost record in said magazine having means at one edge of said table and active only when engaged by a record for effecting lateral movement of said record relative to the other records and also having means for engaging the bottommost record in said magazine with said first mentioned means.

182. In a phonograph, a record rotating table rotatable on a vertical axis and having an upstanding centering pin and unobstructed space above the latter, a magazine carrying a series of superimposed records with their axes laterally offset relative to the table axis and having adjacent portions of said records overlying the adjacent portion of said table during reproduction of a record on the latter, and mechanism for successively supplying laterally into centered position in the unobstructed space above said pin the bottommost records in said magazine.

183. In a phonograph, a record rotating table rotatable on a vertical axis and having an upstanding centering pin and unobstructed space above the latter, a magazine carrying a series of superimposed records with their axes laterally offset relative to the table axis and portions of the same overlying the adjacent portion of said table during reproduction of a record on the lat-

ter, means for successively supplying laterally into centered position in the unobstructed space above said pin the bottommost records in said magazine, and mechanism for successively re-
5 producing said records on said table having a swinging reproducer pivoted at one side of the aligned table and magazine at a point within the longitudinal limits of said table.

184. In a phonograph, a single record rotating table rotatable on a stationary vertical axis and having centering means and an unobstructed space above said centering means, a laterally offset record magazine adapted to support records of different size therein with their central apertures at different distances from said centering means, and means for delivering records from said magazine laterally through said unobstructed space into centered position on said table irrespective of the variation in the distances between the axes of the records in said magazine and said centering means.

185. In a phonograph, a record rotating table rotatable on a fixed vertical axis, a laterally offset record magazine having means for supporting a series of records therein, means for disengaging one edge of records in said magazine and permitting that edge to drop therefrom, and means successively acting upon the disengaged records and directing them bodily laterally toward said table with said edges at the front of the records and movable across the table axis into centered position on said table.

186. In a phonograph, a record rotating table rotatable on a fixed vertical axis and having a centering pin and unobstructed space above the latter, a laterally offset record magazine having means for supporting a series of records therein, means for disengaging one edge of records in said magazine and permitting them to drop therefrom, and means successively acting upon the disengaged records when remote from the table and directing said records bodily laterally toward said table with said edges at the front of the records and movable across the table axis in the space above said pin into centered position on the latter.

187. In a phonograph, a record rotating table disposed on a fixed vertical axis, a record magazine having means for supporting a series of records therein, and mechanism for successively supplying records from said magazine onto said table, and reproducing and discharging the same having a controlling member for said record supplying mechanism movable in a path intersecting the planes normally occupied by a record on said table and controlled by the presence or absence of a record on the latter, respectively, to suspend operation of said supplying means until after the reproduction and discharge of the record thereon or again operate said supplying means.

188. In a phonograph, a record rotating table disposed on a fixed vertical axis, a record magazine having means for supporting records one above another therein, mechanism for successively supplying records from said magazine into centered position on said table and reproducing and discharging the same having a controlling member movable in a path intersecting the planes normally occupied by a record on said table and also having co-operating means controlled by said member and operative to effect operation of said record supply mechanism after each discharging operation so long as said member engages successive records on said table and automatically operative when no record is on

the table to effect a predetermined expedited operation of said mechanism and then stop the latter.

189. In a phonograph, a magazine adapted to receive records in predetermined positions therein, a record rotating table disposed on a fixed vertical axis, mechanism for successively supplying a predetermined number of records from said positions to said table, mechanism for successively reproducing the predetermined number 10 of records supplied to said table, and means for cutting short the normal reproducing time and expediting the delivery of the next record to said table whenever no record is supplied from one or more of said magazine positions to the table. 15

190. In a phonograph, a record rotating table rotatable on a stationary vertical axis and having an unobstructed record delivery space above said axis, a record magazine having means for supporting records therein in laterally offset relation to said table with the adjacent edges of records in said magazine irrespective of their diameter substantially in alignment and the remote edges of records of different diameter differently spaced from the table axis, and means for delivering records of different diameter in said magazine through said unobstructed space into centered position on said table irrespective of the variation in the distances between the axes of the records in said magazine and the table 30 axis.

191. In a phonograph, a record rotating table rotatable on a stationary vertical axis and having an unobstructed record delivery space above the same, a record magazine having means for supporting a plurality of records therein in laterally offset relation to said table with the adjacent edges of records in said magazine substantially in alignment and the remote edges of records of different diameter differently spaced from the table axis, means acting on the edges of the records adjacent said table for separating records of either diameter from the other records in the magazine, and means for delivering separated records of different diameter through different distances laterally above the table into centered position on the latter.

192. In a phonograph, a record rotating table rotatable on a stationary vertical axis and having an unobstructed record delivery space above the same, a record magazine having means for supporting a plurality of records therein in laterally offset relation to said table with the adjacent edges of records in said magazine substantially in alignment and the remote edges of records of different diameter differently spaced from the table axis, means acting on said edges of the records adjacent said table for separating records of either diameter from the other records in the magazine, and mechanism for delivering separated records of different diameter into centered position on the table having record guiding means movable relative to the records and projecting the latter laterally into said unobstructed space and lowering records of different diameter in different lateral positions into centered position on said table.

193. In a phonograph, mechanism for automatically reproducing a series of records including a magazine adapted to receive the records to be reproduced, and having means for enabling all of the records in the latter to be automatically played in sequence, means for enabling any record in said magazine to be removed from said magazine at any time while the mechanism is 75

reproducing another record without interrupting reproduction or requiring repetition thereof or removal of the other records in said magazine, and also means for automatically indicating each record being reproduced and automatically stopping said mechanism upon reproduction of the last record in said magazine.

194. In a phonograph, a record magazine adapted to carry records of different diameter, 10 a laterally offset turntable rotatable on a vertical axis in planes spaced below said magazine, means for rotating said table throughout the operation of the phonograph, means for centering records of different diameter in said magazine 15 on said table while the latter rotates, delivering all records into the space below said magazine and above said table and laterally through said space with their forward edges travelling across the table axis during centering, a reproducer, and 20 automatically operative means co-operating with said centering means to bring the reproducer into operative engagement with the outer edges of records of different diameter when the same are centered on said table by said centering means.

195. In a phonograph, a record magazine comprising co-operating record supporting means adjustable relative to one another to accommodate records of different size, a record rotating table, record feeding mechanism for feeding a record 30 on said supporting means to said table, and reproducer mechanism acting on records on said table and correspondingly adjustable in range by the adjustment of said supporting means relative to one another.

196. In a phonograph, mechanism for successively presenting and reproducing records including a record rotating table disposed on a stationary vertical axis, means for rotating said table about said axis throughout the operation 40 of the phonograph, a swinging record discharging member, reproducer mechanism automatically operative on successive records on said table including a swinging reproducer and means for enabling lowering a part of the latter below the plane of a previously reproduced record on said table, and means operative between reproducing operations of said reproducer and in timed relation to the movement of the part of the latter below said plane for actuating said 45 discharging member and presenting a new record

for reproduction on said table and thereafter depositing said reproducer thereon.

197. In a phonograph, the combination with mechanism for successively presenting and reproducing records including a table disposed on a stationary vertical axis, means for rotating said table about said axis throughout the operation of the phonograph, a swinging reproducer, means for automatically raising the same after reproduction, swinging the same back to initial position, and lowering the same on a newly presented record on said table, a swinging record discharging member, and means for actuating said member to discharge a reproduced record and returning said member to initial position before said reproducer finishes a new record, of means for adjusting said mechanism to present and reproduce records of a different diameter having a manually adjustable control member and co-operating means automatically adjustable upon 20 operation of said control member to make any necessary adjustment of said mechanism for effecting automatic operation thereof on such records of different diameter.

198. In a phonograph, a record carrying support supporting a series of records in horizontal relation one above the other, mechanism for effecting lateral movement of an end record thereon relative to the remaining records comprising means for freeing said record for lateral movement relative to the other records in advance of lateral movement of said record and while lateral movement of the other records on said support is inhibited and means for moving said freed record bodily laterally relative to the other records, automatic reproducer mechanism, means for actuating said first mentioned means in timed relation with said reproducer mechanism to free said record and subsequently actuating said second mentioned means to move said record laterally following a reproduction by said reproducer mechanism, said first mentioned mechanism being automatically disposed ready to effect lateral movement of the next end record prior to completion of the next operation of said reproducer mechanism and means operable in one operation for adapting the phonograph for automatic reproduction of a series of records of a different diameter.

CLEMMA R. RANEY. 50

CERTIFICATE OF CORRECTION.

Patent No. 1,988,180.

January 15, 1935.

CLEMMA R. RANEY.

It is hereby certified that error appears in the printed specification of the above numbered patent requiring correction as follows: Page 1, first column, line 2, strike out the word "been"; line 5, after "reproducing" insert a comma; and line 42, for "to" read of; and page 4, first column, line 40, after "57" insert a comma; page 5, second column, lines 12 and 13, strike out the words "on the under side"; page 6, first column, line 33, after "engage" insert a comma; and line 46, for "the" read this; page 8, second column, line 34, claim 8, for "mechanism" read mechanisms; page 11, second column, line 69, claim 52, after "from" insert a comma; page 15, second column, line 45, claim 113, after the syllable "nism" and before the comma insert the words having record centering means; page 16, first column, line 22, claim 117, after "automatic" strike out the comma; page 19, first column, line 26, claim 154, for "diameters" read diameter; page 20, second column, line 50, claim 171, for "thereby" read by a record being reproduced on said table; page 22, first column, line 52, claim 187, after "table" strike out the comma; and that the said Letters Patent should be read with these corrections therein that the same may conform to the record of the case in the Patent Office.

Signed and sealed this 19th day of March, A. D. 1935.

Leslie Frazer
Acting Commissioner of Patents.
